METHOD AND APPARATUS FOR MAKING PILE FABRICS

Application filed August 16, 1928. Serial No. 299,902.

This invention relates to a pile fabric material, and to a method and apparatus for making the same. More particularly the invention comprises a cemented pile fabric which is adapted for carpets, rugs and similar material and which is particularly adapted for upholstery and similar special uses because of certain peculiar properties of the product when made in accordance with the method and apparatus herein disclosed. When so made the pile material has a marked uniformity and a higher density than is possessed by any other product heretofore made as far as I am aware. The product may be readily flexed in all directions without gapping or the showing of lines or openings whereas products heretofore made show lines or openings which are more marked in one direction than another, and moreover, the product of my invention is made in a manner so that there is substantially no loss of pile material, and a very considerable economy is thus affected over processes heretofore employed for the making of analogous products. By the use of my invention, the pile element material upon the backing element may be originally produced of substantially even height so that substantially no shearing is required in order to complete the product. The process which I have disclosed is also adapted to form a carpet or upholstery material in which the amount of pile forming material employed per unit of area may be less than is possible with any other process, and the amount of pile element material may be reduced to a minimum by employing a minimum pile height and by evenly distributing the material over the backing surface to produce the desired low pile density.

One of the objects of the present invention is to provide a new and useful pile fabric product which may be made with a higher pile density and with greater uniformity of pile than products heretofore produced and which has certain novel characteristics adapting it particularly for upholstery material.

Another object of the invention is to provide a method for making a pile fabric material by cementing suitable pile elements to a backing in a manner so as to be evenly and

uniformly distributed over the surface of the backing, and to provide a method of making a cemented pile fabric in which the pile elements may be made any desired length, and which is particularly adapted for the making of upholstery and other pile fabrics in which the pile material is comparatively short and of uniform density.

Another object of the invention is to provide a method of making a cemented pile fabric in which any character of fibre or pile element material may be used; or more specifically, to provide a method adapted for the use of spun or unspun fibres which may be attached to a flexible backing material in such a manner that the ends only of the spun strands or the unspun fibres are attached to the backing, and furthermore, in a manner to obtain a uniform distribution of the pile elements over the surface to which they are attached.

Another object of the invention is to provide a new and useful apparatus which is particularly adapted for the making of cemented pile fabrics from yarn or other form of spun fibres or from loose or unspun fibres, and which is adapted for the making of cemented pile fabric of substantially any desired pile density and pile height, with uniform distribution of the pile elements over the surface to which they are connected.

Another object of the invention is to provide a form of machine which is applicable to the making of cemented pile fabrics from either spun or unspun fibres, and which is particularly adapted for the making of cemented pile fabric by the use of a batt composed of loose fibres of any kind, including the varieties unadapted for spinning, such as goat hair, for example.

Another object of the invention is to provide a machine which is applicable to the making of cemented pile fabrics from pile elements which are to be cut or obtained from elemental material such as yarn, cord, twine, strands or fibres in the form of a batt, or individual fibres associated in any other way, and which serves to cut or separate fibre elements and arrange them in fixed relation with substantially all of the ends of

the fibres exposed so as to permit their attachment to a backing, while rigidly held in place.

Another object of the invention is to provide a form of apparatus for the production of cemented pile fabric material which is adapted for cementing a mass of substantially parallel upstanding fibres either to a single backing on one surface of the fibre mass, or to two backings which are attached, on the opposite exposed surfaces of the mass, to the ends of the fibres, whereby the pile elements may be cut in a plane between the two backing elements to obtain two separate pile fabric products.

Another object of the invention is to provide a form of machine which is particularly adapted for feeding a material, from which pile elements are to be obtained, in such a manner as to maintain the material under control, so that each individual section or fibre portion which is to be severed from the material, may be maintained in fixed position during the cutting or severing action and maintained under control thereafter, so as to prevent disturbance of the fibres until it is attached to a backing; and to provide means for advancing cut sections in a manner to maintain the fibre ends on each side of the sections in substantially a single plane and to advance the severed sections in a mass, without disturbing the relative position of the fibres with respect to each other, whereby a backing material may be attached to either one or both ends of the fibres.

Another object of the invention is to provide a form of apparatus particularly adapted for controllably feeding a body or mass of material from which pile elements are to be formed, and for cutting or severing sections or portions of the body or mass of material in substantially a single plane while maintaining the remaining mass under automatic control, and while maintaining the severed material in controlled fixed relation by being clamped or securely held during and subsequent to the cutting or severing operation until the severed material is cemented to a backing member.

Another object of the invention is to provide an apparatus adapted to controllably feed a pile element forming material and to cut sections from such material in a sequence of operations in which the severed sections are collected side by side to present the fibre ends in substantially two parallel planes, the fibres of the mass lying at substantially right angles to the planes; such apparatus including means for feeding the mass of fibres into contact with backing elements and for cementing the backing elements to the fibre ends by means of a vulcanizable cement, together with means for vulcanizing the cement material, whereby the fibre elements become permanently attached to the backing mem-

bers, means being provided to hold the sections of material under lateral compression to obtain substantially any desired pile density.

Another object of the invention is to provide a form of apparatus which is adapted for either the use of separators to controllably feed sections of cut material through the machine in contact with a backing or backing element to be applied to the fibres, or for use without separators in such a manner that the fibres of the cut sections may be maintained under control in passing through the apparatus, and cemented to a backing element on each surface of the mass of cut sections, whereby after the fibres are permanently cemented to backing elements the fibres may be readily cut in a plane between the backing elements to provide two separate and distinct pile fabric products.

Another object of the invention is to provide means whereby sections or unit masses of fibres having their ends exposed and maintained in substantially parallel planes may be packed under pressure into a chamber, and means to permit withdrawal of the packing means without releasing the packing pressure on the mass of fibres is the chamber.

In accordance with this object, I preferably provide a packing plunger having recesses or grooves extending inwardly from the face of the plunger at an angle and provide means for replacing the plunger pressure, or substituting for the plunger a series of pins which are moved angularly into place in the grooves or recesses in the face of the plunger, permitting it to be withdrawn leaving the pins in pressure contact with the mass of fibres at the entrance end of the cut-section chamber, thus permitting the batt or pile element material to be fed into place for the next cutting operation, and permitting a cycle of operations to take place, including cutting the batt material, inserting the cut-section into the cut-section chamber by means of the plunger, and withdrawing the pins when the plunger has moved up to the entrance end of the cut section chamber so as not to block the entrance to the chamber, thereafter substituting the pins for the plunger when it has moved into its extreme forward position without releasing the pressure on the mass of cut sections in the chamber, so as to hold the cut sections therein, and withdrawing the plunger to permit the feeding of the batt into place for the next cutting operation and permitting the feeding of separators into place when separators are employed in the preferred mode of carrying out the invention.

With these and other objects in view which will be apparent from the following description, the invention comprises the various features hereinafter described and more particularly defined in the annexed claims.

In carrying out my invention I preferably employ the form of machine shown in detail in the accompanying drawings although it is to be understood that various parts thereof may be modified in a manner as will be apparent to those skilled in the art without departing from the invention as hereinafter defined in the claims. By means of the form of machine illustrated in the drawings, the various method steps hereinafter fully described, may be carried out and the product of my invention may be made.

The form of machine hereinafter fully described operates to feed the elemental material which is to constitute the pile elements of my product, and to rigidly hold the pile elements in the desired relation subjected to lateral pressure to provide the desired pile density, the material being preferably fed into contact with flexible backing members, one on each side of the mass of pile elements, the pile elements being cemented thereto, preferably by the use of a vulcanizable rubber cement, which is subsequently vulcanized to permanently attach the ends of the pile elements to the backing members, and the pile elements being cut in a plane between the backing members to obtain two pile fabric products.

In the operation of the machine above referred to, the pile elements are preferably formed by cutting a batt into suitable sections to provide pile elements of the desired lengths in the making of the pile fabric product. Although the operation of my apparatus will be described mainly in connection with the use of a batt or body of loose fibre elements, it is to be understood that the machine is equally applicable to, or operative with, yarns or other suitable material as above stated, and I do not desire to be limited in any manner with reference to the use of any specific material, except as herein-after defined in the claims.

If a batt comprising goat hair, for example, is employed in the making of my pile fabric product, the fibres, before being fed to the machine, may be arranged in a general longitudinal direction of the batt by a drawing or straightening operation, or obviously the fibres coming from the doffer of a carding machine, for example, may be laid in a general parallel direction longitudinally of the batt by means of a suitable form of lapper.

After a batt of a suitable width and thickness has been formed, it is fed into the machine of my invention by any suitable feeding mechanism, and is brought into position in connection with the cutting element thereof to be cut into the desired lengths. In the operation of the machine it is practically essential that the batt portion to be severed be held adjacent the point of cutting during the cutting operation, and maintained under con-

trol thereafter to prevent relative displacement of the fibres until after the section has been passed into place in contact with the remaining mass of fibres. The batt is preferably rigidly held at the portion to be cut both below and above the point of cutting, and preferably both the cut section and the remaining batt portion are rigidly held thereafter so as to prevent disarrangement of the fibres and to maintain the batt feeding under positive control.

After a batt section has been severed from the remaining body of the batt, the section is preferably maintained in upright or upstanding position and is then united under controlled lateral pressure to the main body of fibres which is to be connected to the backing, and is then transferred into contact with a backing material preferably on both sides of the pile element body in contact with the exposed ends of the fibre elements and is cemented thereto by means of cementing material so that the pile elements are individually united to the backing at both ends thereof.

After the pile elements have been permanently fastened to the backing material, the fibre elements are cut by any suitable cutting means in a plane parallel to the backing and the usual finishing operations may be carried out to obtain the desired pile height upon the backing members to form the finished product.

In the accompanying drawings illustrating the preferred embodiment of my machine:

Fig. 1 is a diagrammatic side view of the pile fabric forming apparatus of my invention showing the essential elements thereof for forming the cemented pile fabric product, comprising a part of the means for feeding the batt or pile forming material into the machine, means for cutting the material, means for feeding cut sections of material into a chamber between separators to hold the fibres in place, means for applying a cementing material to the ends of the fibres, means for applying a fabric or other flexible material to the ends of the fibres or pile elements, means for applying heat and pressure to produce vulcanization of the cementing material to permanently attach the fibres to the backing, and means for cutting the pile elements and for carrying out the finishing operations to produce the pile fabric product.

Fig. 2 is a sectional view in elevation taken on section line 2-2 of Fig. 5 showing the front end of the machine as it appears from the right, and showing the detailed arrangement of the cams and cam levers operating the feeding jaws, plunger and other associated parts of the mechanism;

Fig. 3 is a fragmentary sectional view in elevation of the parts of the mechanism for cutting sections of the batt or pile forming material and for feeding the cut sections of

the material to the cut section chamber, a batt being shown in the position to which it is moved by the feeding jaws before being clamped by the clamping jaws;

6 Fig. 4 is a detailed side view of a portion of the machine taken on the line 4—4 of Fig. 5, parts of the machine being shown in section to illustrate the preferred mode of attaching the pressure plates which are employed together with conveyor belts operated at predetermined rates for producing and maintaining a predetermined back pressure in the cut-section chamber by providing friction pressure upon the ends of the pile ele-
10 ments;

Fig. 31 is a detailed view taken on the section line 31—31 of Fig. 29 in the direction of the arrows.

45 The main elements of the machine embodying my invention comprise the following:

A pair of jaws are employed for feeding the batt or pile element material into the machine, and clamping means are used for holding the material in place on both sides 50 of the cutting mechanism during the cutting operation by which a portion of the pile forming element material is severed from the main body of the material.

55 On the feed side of the cutting mechanism clamp jaws are preferably employed for holding the pile element material during the cutting operation and also to hold the material during the time that the feeding jaws are moved into a new position thereon to obtain

60 a new grip for feeding.

On the other side of the cutting mechanism, means are employed for rigidly holding the batt portion or pile element section to be severed to prevent displacement of the fibres in the section during the cutting opera-

tion; an inserting means, preferably a plunger, is also provided to move the severed section, while still controllably held to prevent disturbance of the fibres, into the cut-section chamber to join the main body of the cut fibre elements; in addition, cooperating means are provided for retaining the cut elements in the cut-section chamber and to permit removal of the plunger or inserting means from the mouth or entrance to the cut-section chamber, so as to clear the space for further feeding of the batt or pile element material into position in front of the cutting mechanism for the next cutting operation.

In accordance with my invention, the feeding jaws are adapted to grip the material laterally and then move it longitudinally, preferably downwardly in a vertical direction as illustrated in the drawings showing the preferred embodiment of my invention, the material being intermittently moved a predetermined distance in accordance with, or corresponding to, the desired height of the pile material in the product to be made.

The form of clamping jaws which I employ are preferably operated in a manner so as to move only in a plane at right angles to the longitudinal direction of movement of the batt, and in the preferred form of my machine, only in a horizontal plane so as to grip the material at intervals and to hold it during the cutting operation and during the time that the feeding jaws are released from gripping contact with the batt. The clamping jaws might obviously be made to move not only in a horizontal direction, or at right angles to the batt or material operated upon, but also vertically, or longitudinally of the batt, to feed or assist in feeding the batt or pile element material through the machine.

Another element of my mechanism comprises the cutting means, above referred to, for cutting sections of batt or the fibre element material, which preferably comprises a series of associated rollers adapted to cooperate with a knife edge, the cutting operation being accomplished by feeding the batt or fibre element material between the rollers and knife edge and rapidly passing the cutting rollers over the batt in pressure contact therewith to sever the fibre elements in the manner hereinafter more fully described, the batt or fibre element material being securely held on both sides of the cutting mechanism during and after the cutting operation, so that after the material has been cut and a section severed from the material, both portions of the batt or fibre material are maintained under control for subsequent operations.

Another element of the machine comprises a chamber into which the cut sections or severed material, while still maintained under control to prevent disturbance of the

fibres in the severed sections, may be passed or forced, together with means cooperating therewith to retain the cut sections under lateral pressure after the means for forcing the material into the cut-section chamber has been withdrawn or removed.

- In order to force the material into the cut section chamber, a plunger is preferably employed which operates at desired intervals, or 10 in a desired sequence with other operations, to move the cut sections into place in the cut section chamber. In order to maintain the desired lateral pressure on the cut sections in the cut-section chamber, a back pressure is 15 preferably employed which may be provided by means of movable belts associated in a manner to form a chamber into which the severed sections from the cut-section chamber are conducted, pressure contact of the belts 20 with the sections being attained by means of pressure plates positioned on the belts so as to exert pressure inwardly against the portion of the belts adjacent the inner chamber formed thereby in the manner hereinafter described, 25 the belts being operated at the same speed as that at which the cut sections are fed into the cut-section chamber, lateral compression being developed or varied by controlling the 30 rate of feed of cut sections or by varying the thickness of the batt, thus producing the desired pile density.

The means which I preferably provide for holding the cut sections in place in the cut-section chamber when the packing plunger is 35 withdrawn comprises a series of spaced pins adapted to be raised and lowered at the entrance to the cut-section chamber, the plunger having a series of grooves in its face into which the pins may be passed while the plunger 40 is still in its extreme forward position at the entrance to the cut section chamber, thus permitting the plunger to be withdrawn without having to disturb the position of the pins when in the raised position in front of the 45 cut-section chamber, whereby the pins are substituted for the plunger to hold the cut-sections in the cut-section chamber.

Another element of my invention in its preferred embodiment comprises the use of 50 a series of separators or separator plates to hold the cut-sections of fibres in place during the cutting operation and in subsequent operations, so that as a section of batt is cut in the manner hereinafter described, the fibres 55 are rigidly held against displacement between two separators or separator plates and may be transferred into the cut-section chamber without material disturbance of the fibres, thereby holding the fibre ends in substantial- 60 ly a single plane on each side of the united mass of fibre sections.

The height of the separators is preferably slightly less than the corresponding dimension of the cut sections, so that the ends of the 65 transferred fibres are exposed both above the

top and below the bottom of the separators, thus permitting cementing a flexible backing in place at the exposed surfaces of the fibres, or in other words at the fibre ends projecting above and below the separators. The separators, having sections of batt clamped or rigidly held in place between them, are preferably held under control or suitably guided during movement of the batt sections through the cut-section chamber, through the cement applying chamber and through the vulcanizing chamber or chambers until vulcanization is complete, the movement of the separators being preferably controlled by means of suitable guides at the sides of the chambers serving to maintain the separators and the cut sections in fixed relation in the passage through the apparatus. The body of cut sections is thus uniformly maintained under control after the cutting operation is effected 80 and may be readily treated in subsequent operations to apply cement material to the exposed surfaces of the fibres and to apply a backing members permanently in place by vulcanization or other operations without 85 disturbing the main body of the fibres held rigidly in place between the separators.

It is to be understood that although separators are preferably employed, the form of machine hereinafter described is operable 95 without the use of separators and that by omitting them a higher pile density may be obtained in the finished product.

The separator feeding device preferably 100 comprises a magazine separable from the main body of the machine so that a magazine containing separators may be inserted into the machine at intervals as required. After the separators have passed through the apparatus in the operation of making the pile 105 fabric product, they may be suitably withdrawn from the finished or partly completed product and inserted into a magazine so as to keep up the cycle of operations through the machine. Means are provided in the machine for feeding the separators from the separator magazine into place in front of the portion of the batt or the pile element material which has been fed into place ready for the cutting operation, the separator being fed 110 forwardly into place by means of the plunger, in the preferred form of my invention, whereby as the alternate feeding of a separator into place in front of the batt or pile element material and the cutting operation take place, the individual cut sections are separated by means of separator plates, or in other words the cut sections are spaced alternately with separators serving to hold the cut sections rigidly in place in the cut section chamber in a manner illustrated in detail in Fig. 13 of the drawings.

Referring more in detail to the drawings, the general method of making my product 130

may best be outlined with reference to Fig. 1 of the drawings.

The pile forming element material 9 is fed downwardly by feeding jaws 1 and 2 until the lower edge of the fed material contacts with the floor at the entrance to the cut-section chamber 92. The clamp jaw 30 is positioned so as to guide the fed material over the knife edge 4 and so as not to interfere with the feeding of the material. The clamp jaws 3 and 30 are then operated to hold the portion of the batt above the knife edge rigidly in proximity thereto and the plunger 5 is moved forwardly with a separator 8 positioned on its face, the separator being guided by means of the lateral guides 80, and when the plunger and separator associated therewith have been moved into position against the batt or element 9, the holding pins 7 at the entrance to the cut-section chamber 92 are withdrawn and the back pressure in the cut-section chamber moves the last inserted separator in the cut-section chamber against the lower portion of the batt 9 opposite the plunger and separator held on the face of the plunger. The plunger is now in its intermediate position and the batt or pile element material is held above the knife edge 4 by means of the clamp jaws 3 and 30 and below the knife edge by means of two separators one in contact with the face of the plunger 5 and the other in contact with the last inserted section of batt material in the cut-section chamber 92, the parts being in the position shown in Fig. 8 except for the cutting rollers 41.

The operation of cutting the batt over the knife edge 4 takes place by a cam and lever action, serving to move the cutting rollers 41 in contact with the batt at the knife edge 4, and automatic power operation to bring the rollers across the batt at the knife edge, whereby the fibres of the batt, are pinched off or cut off in the manner hereinafter more fully described. The rollers are then brought away from the batt by a cam and lever action and the plunger 5 is then moved forwardly into its extreme forward position into the entrance to the cut-section chamber 92 so as to insert the last cut section into the cut-section chamber. The pins 7 on the bar 71 are then raised upwardly into the slots 53 in the face of the plunger 5 so as to permit withdrawal of the plunger and retaining the cut sections within the cut-section chamber by means of the pins 7.

While the clamp jaws 3 and 30 are holding the lowered portion of the batt 9 in position, the jaws 1 and 2 are moved upwardly to obtain a new grip on the batt for feeding, and after the jaws 1 and 2 have gripped the batt, the clamping elements 3 and 30 may then be withdrawn and the batt is then fed downwardly again as above described and

the operations repeated as explained more in detail hereinafter.

As the cut sections are fed one by one into the cut section chamber 92, they are gradually moved forwardly until they pass rollers 935 and 936 at which point they are fed into a chamber 93 formed by belts 933 and 934, the upper belt 933 passing over the rollers 935 and 937 and the belt 934 passing over the rollers 936 and 938. At the entrance to the chamber 93 between the belt portions passing over the rollers 935 and 936 and the inwardly projecting ends of the walls 911 and 912 of the cut-section chamber, a rubber cement material of the character adapted to be vulcanized is preferably fed into contact with the ends of the fibres of the cut sections through feed nozzles 921 and 922 or other suitable feeding means so as to form an even surface coating at the ends of the fibres. The belts 933 and 934 are preferably power operated and are moved at the same rate as that of the cut sections being fed through the cut-section chamber, the sections of the belts 933 and 934 adjacent the cut-sections being pressed into pressure contact with the body of fibres by means of pressure plates 931 and 932 as will be hereinafter more fully described. The belts serve to distribute the rubber cement material over the surface of the cut-sections and to work it into the ends of the fibres a suitable distance depending upon the character of the cementing material employed. The amount of penetration of the cement material into the fibre body may obviously be controlled by selecting a rubber cement material of the proper consistency. It will be obvious that the thinner the cement material employed the greater the penetration from the exposed surface portions of the fibres to the interior body and conversely, the greater the body or thickness of the cement material employed, the less will be the penetration into the body portion of the cut sections. It will be obvious also, that the degree of penetration will vary with the amount of cement material employed.

After passing through the back pressure chamber 93, the cut sections move onwardly through a guide section, comprising plates 939 and 940, by means of which the cut sections are passed from the chamber 93 into the chamber 94 and which serves to maintain the fibre mass under control to prevent disturbance of the fibres of the cut sections. In order to assist in drying the cement material, hot air is preferably introduced through the guide plates 939 and 940 through passageways as indicated in the drawings, or, if desired, heat may be applied independently by any suitable means to assist in drying the cement material, air being preferably introduced in order to carry away the vaporized material, such as water vapor or solvents.

The chamber 94 is similar to the chamber 130

93 being formed by belts 945 and 946 passing over rollers similar to rollers 935, 937, 936 and 938 respectively, the sections of the belts adjacent the chamber being pressed inwardly by means of pressure plates 949, operated in a manner similar to the plates 931 and 932, the operation of which is herein-after described in detail.

- In order to apply the backing material to 10 the ends of the fibres at both sides of the mass of cut sections passing through the chamber 94, flexible backings are preferably fed from rolls 941 and 942 into contact with cement applying devices 943 and 944 which 15 apply the vulcanizable rubber cement material uniformly over the surface of the backing material 947 and 948 to be passed into contact with the exposed surfaces of the fibres, the cement material being preferably 20 dried before passing into contact with the ends of the fibres by means of suitable drying nozzles 913 and 914 through which hot air may be passed. Obviously the cement material may be applied to the backing previously 25 to being formed into rolls, and the backings may be thereafter fed from rolls directly over the forward rolls of the chamber 94 with the cement treated surface exposed to the fibre ends of the cut sections. 30 The plates 949 serve to apply any desired inward pressure in the chamber 94 to cause adherence between the backing material and the cemented exposed surfaces of the cut sections. The belts 945 and 946 are operated 35 at the same rate as that at which the cut sections pass through the chamber 94 so that after the fibre ends come into contact with the backing material, there is no relative movement between the backing material and 40 the ends of the fibres. From the chamber 94 the cut sections move with the backing material 947 and 948 through a guide chamber formed by plates 955 and 956 which serve to 45 conduct the material into the chamber 95 between the belts 951 and 952 upon which platens 953 and 954 are applied to produce vulcanization of the rubber cement material and cause permanent attachment of the cut sections to the backing. The platens may be 50 heated to any desired temperature by means of steam heat, or any means old in the art may be employed for producing vulcanization under pressure as will be apparent to those skilled in the art. From the vulcanizing 55 chamber 95 the material passes into the chamber 960 of the separator removing device 96, any suitable means being employed for pulling out the separators or separator plates one by one or in sections as may be 60 desired. Obviously, the separator plates may be removed by hand, or the removal may be readily accomplished mechanically by means of one of the guide members 80 registering 65 with the corresponding groove in the separators, the guide being arranged to pass out-

wardly at an angle of about 30° so as to gradually draw out the separator plates from the adjacent sections of cut fibres, leaving the cut sections attached at their upper and lower ends to the backing material 947 and 948.

After the separators have been removed from between the cut sections, the material is passed over rollers 961 and 962 into contact with a cutting device 97 which operates to 75 slit or cut the fibres at substantially a plane midway between the backing members 947 and 948 after which the separated portions may be fed over a guide roll 971 into contact with a tigering device 972, and thereafter the 80 surface may be sheared by any suitable form of device 973 and the finishing operations may be carried out in any desired manner such for example as by a steaming operation 85 by means of the apparatus indicated by 974 and a final shearing step by means of the shearing device 975 indicated in the drawings. If preferred, the product 98 after being cut by the cutting mechanism 975 may be rolled or thereafter finished in any desired manner, 90 or the material may be rolled immediately after cutting by the cutting device 97, and thereafter treated in any suitable way including printing or other treatment as will be apparent to those skilled in the art.

The details of operation of the machine and construction of the parts will now be described with reference to the drawings:

The portion of the apparatus by means of which the cutting of the pile element material and the feeding into a chamber between separators is accomplished, forming a body or mass of upstanding pile element material in the chamber, may be referred to as the pile forming machine, as distinguished from the remaining portion of the apparatus comprising the cement applying portion thereof carried out in the chamber 93, the backing applying portion, the vulcanizing part of the apparatus, the separator removing portion, the cemented pile slitting portion of the apparatus and the part thereof for carrying out the finishing operations.

The pile forming element material, as batt 9, may be fed from a chute 900 (see Fig. 5) connected to portion 902 of the machine through brackets 901 for example, into the feed jaw members 1 and 2 (Fig. 2) through the guide plates 10 and 20 connected respectively to the jaws 1 and 2.

The jaw 1 is preferably integral with a member 120 (see Fig. 7) which moves in vertical guides 122 in a block 18, which is horizontally movable in guides 182 (see Fig. 5) in the frame of the machine, being actuated by means of a cam 11 mounted on the cam shaft 24 and operating through a bell crank lever pivoted on the rod 15 and having an arm 17 connected to the block 18 through the pin and slot connection 16 and the arm 13 (Fig. 2).

having the roller 12 mounted thereon which engages the surface of the cam 11. A raised surface portion 118 of the cam 11 operates through the lever to move the block 18 against the force of the spring 140 on the rod 14 which is rigidly mounted on a part 190 of the frame 19 of the machine. In its horizontal movements the jaw 1 slides on one or more (preferably two) pins 200 (see Fig. 2) which are rigidly connected to the jaw 2, the pins passing through the openings 100 in the jaw 1, thereby permitting horizontal movement of the jaw, the part 120 connected to the jaw 1 sliding in vertical guides 122 in the part 18, thus permitting vertical movement of the jaw 1 with the jaw 2. In the operation of the jaws 1 and 2, therefore, the jaw members operate together in the same horizontal plane.

20 The jaw 2 is integrally connected to the bar 27 which moves in vertical guides 29 (see Figs. 11 and 2), and has a rod 270 connected thereto to which the vertical rod members 26 are attached which are pivotally connected at 25 to the levers 23 (see Fig. 12) which are pivoted at 15 and are operated by means of the cams 21 (see Fig. 11) through the rollers 22 connected to the levers 23. Springs 28 connected to the ends 260 of the levers 26 and fastened to pins 192 in the frame of the machine 19, (see Fig. 12) keep the rollers 22 in contact with the surface of the cams 21, serving to positively actuate the jaw 1 in accordance with the movement of the cams.

35 The cams 21 and 11 are preferably mounted upon the same cam shaft 24, being preferably keyed thereto, so that by having the jaws properly set the raising and lowering and the opening and closing movements of 40 the jaws will be interdependent and take place in predetermined desired relation to clamp and move the batt vertically downward and then release the batt by outward movement and return to the raised position 45 for a new grip. These movements are necessarily coordinated with movements of other parts of the machine as will hereinafter be fully described.

50 The clamp jaws 3 and 30 serve to hold the batt 9 during the cutting operation above the knife edge 4 and also to hold the batt while the jaws 1 and 2 move laterally away from the batt and upwardly to obtain a new grip thereon. The clamp jaw 3 (see Fig. 9) is preferably actuated by the cam members 33 which operate on rollers 34 connected to levers 36 which are pivoted on the rod 15, the upper arms 35 of the levers 36 being connected at the pivots 38 to link arms 37 which are pivotally connected by means of pivots 39 to the casting integrally connected with the jaw 3. The cams 33 are preferably of the open type and in order to obtain positive movement of the levers 36 to which the clamp jaw 3 is connected, it is necessary to maintain

the rollers 34 in pressure contact with the surface of the cams through at least a portion of their movement, spring members 314, mounted on rods 316, being employed, the rods 316 being mounted on the frame of the machine (see Figs. 6 and 9) and the springs being held in place on the rods by means of the nuts 318 at one end of the rods, and by means of a sleeve 310 at their other end, the sleeves being slidably mounted on the rods and connected to the body portion of the casting on which the clamp jaw 3 is mounted or to which it is integrally connected. By this means the clamp jaw 3 is maintained in pressure contact with the batt or pile element forming material and is thus self-adjusting for different thicknesses of the material.

25 The clamp jaw 30 comprises preferably a bar extending laterally across the machine and connected to side arms pivoted at its upper end at 32 so that the jaw 30 may be swung inwardly by means of the spring 304 (see Fig. 2) acting upon the lower end of the jaw member. In order to prevent the member 30 from being swung inwardly too great a distance, stop members 300 are connected to the side members of the plate 30 as indicated more particularly in Fig. 12 of the drawings. These stop members are made 30 adjustable in position by means of nuts 302, whereby the length of the pin 300 may be varied, and the outward swinging of the lower part of the jaw member 30 will be limited, the ends of the pins striking against 35 an adjacent part of the frame 19 of the machine.

Below the knife edge 4, the batt is held in position during the cutting operation by means of a separator on each side of the batt, as indicated more particularly in Fig. 8 of the drawings, the pins 7 being in the lowered position, and the plunger 5 being moved with its adjacent separator into pressure contact with the part of the batt below the knife edge. 40 The plunger 5 is moved in guides 50 as will be seen from Fig. 28 of the drawings, and extends preferably across the entire width of the machine, corresponding to substantially the length of a separator. The plunger has 45 grooves 503 (see Fig. 24) at the sides thereof adapted to pass over the guide members 80 upon which the separators are mounted in passing through the passageway to the cut-section chamber and through the cut-section chamber and subsequent parts of the apparatus.

50 Referring to Figs. 9 and 28 of the drawings, the connection between the plunger and the arms 56 of the bell crank levers 54 are clearly shown, the levers being connected through links 58 pivotally connected to the arms 56 at the pivots 59. On the arms 55 of the bell crank levers are rollers 52 which move in grooves 510 of the cams 51, thereby 55

serving to control the forward and return movements of the plunger 5.

The pins 7 which are alternately raised and lowered provide support in their raised position for the cut-sections at the entrance end of the cut-section chamber 92 when the plunger 5 is withdrawn away from the entrance to the chamber; these pins are preferably mounted diagonally on the pin bar 71 in the manner illustrated more particularly in Fig. 12 of the drawings, the pins being shown in the raised position, being projected diagonally through openings 76 in the plate 77 which forms the floor of the entrance to the cut-section chamber. In order to permit moving the pin bar or plate 71 in the diagonal direction of the openings in the plate 77, the pin bar is mounted in guides 70 so as to move forward and back from the position shown in full lines to the retracted position shown in dotted lines at 71'. The movement of the pin bar is accomplished by means of the levers 73 (see Fig. 7), which are preferably pivoted at 15 and have rollers 74 mounted at the ends of the arms or levers 73 which cooperate with the openings 78 in the bar 71, the openings being of elongated form, as shown in Fig. 12, to permit relative lateral movement of the pin bar as the levers are raised and lowered in a vertical plane. In order to operate the levers 73, cams 72 (see Fig. 5 and Fig. 7) having grooves 720 therein are mounted on the cam shaft 24, the levers being positively actuated by means of rollers 75 mounted on the levers 73 and running in the grooves. By the means described the pins 7 are raised and lowered at intervals in a predetermined sequence of operations, as hereinafter explained, the raising and lowering being dependent upon the form of the grooves in the cams 72 as will be apparent from Fig. 7 of the drawings.

In the operation of my machine, separators 8 are preferably employed for firmly holding or clamping the lower side of the batt, during the cutting operation, between the plunger and the mass of cut sections in the cut-section chamber, and also to hold the sections of fibres, after they have been severed, in the cut-section chamber, so as to maintain the fibres in undisturbed relation after the cutting operation, whereby the fibre ends may be presented in uniform plane surfaces to the backing elements which are to be applied to the fibre ends. If the position of the fibres after cutting were to be disturbed or changed the fibre ends would be moved out of the same plane and the fibre mass could not be uniformly cemented to a backing. It is essential that if the machine is operated without the use of separators, the batt section to be severed must be rigidly held during the cutting operation to obtain a uniform cut and must be joined with the cut sections of fibres in the cut-section chamber without disturbing

the position of the fibres in the cut-section or in the mass of cut-sections in the cut-section chamber. The means which I provide, as herein described, serve to accomplish this purpose whether the machine is operated with or without the use of separators.

Referring to Fig. 20, the cooperating parts by means of which separators are fed into place in contact with the batt comprise a chamber 82 in which the separators 8 to be fed are stored in a magazine 81 adapted to hold a large number of the separators, and which is adapted to be readily inserted into or placed in the machine. The separators may obviously be gathered or collected and inserted into magazines as they are withdrawn by the separator removing device 96, from between the sections which have been cemented to a backing or backings. The magazines 81 are preferably of a form shown in vertical section in Fig. 21, and in top plan view partly in section in Fig. 20, in which a magazine is shown in feeding position in the separator feeding chamber 82. In order to feed the separators, a magazine is inserted in the machine in the opening 820, the magazine being moved inwardly against the stop 821 in which position the spring pressed pin 822 connected to the magazine moves into a corresponding opening 823 in the casing portion 87 of the machine, to hold the magazine in place during the separator feeding operation. In order to positively move the separators forward into position to be fed by the lifting pins 6, one or more spring pressed feeding rods 85 are provided, which move the separators 8 in the magazine along the guide rails 80' on each side of the magazine, the feeding rods being preferably mounted in cylindrical casings 88 which are attached to the casing portion 87 in any suitable way, such as by means of a screw threaded connection. The rods 85 pass through openings 86 in the casing portion 87 and press against the movable feeding member or sliding side portion 810 of the magazine which is mounted on the side rails or guides 80' and gradually moves toward the separator feed opening 69 (see Fig. 23) as the separators are fed one by one into contact with the batt sections. On the end of each rod is a nut 89 to limit the inward movement of the rods. Between the end of the rod casing 88 and a stop member 850 is a spring member 851 which forces the rod 85 inwardly providing the required separator feed pressure.

In order to feed the separators up in front of the plunger 5 from the magazine 81, separator lifting pins 6 (see Figs. 7, 22 and 24) are provided, which are preferably mounted on a base member 65, which is raised and lowered as required by rods or levers 62, which are preferably pivoted on the shaft or axis 15 and are operated by means of one or more cams 66 (see Figs. 7 and 5) mounted

on the cam shaft 24, the cams 66 having grooves 660 therein in which the rollers 61, connected to the lever arms 62, operate. At the operating end of each of the levers or arms 62 are rollers 64 which operate in corresponding grooves or openings 650 in the pin bar 65 (see also Fig. 24).

In order that the plunger 5 may move forward in the raised position of the pins 6 over the ends thereof, a series of longitudinal grooves 502 are provided in the lower face of the plunger (see Fig. 24) corresponding in number and position to that of the pins 6.

The pin bar 65 is shown in its lowered position in Fig. 9 of the drawings, in which it will be noted that the separators 8 in the separator magazine 81 have been forced forward by the spring pressed rods 85 so that the foremost separator is forced against the opposite wall above the face 60 of the pins 6, whereby when the pins 6 are moved upwardly through the openings 63 (see Fig. 22) in the wall 77, the top 60 of the pins 6 will engage the lower edge of the foremost separator, and the separator will be moved upwardly through the opening 69 (see Fig. 23). During the upward movement of the separator it is confined in the narrow space 69 and cannot therefore be upset or tipped out of position; the separator 8 in its upward movement passes through the intermediate position shown in Fig. 2 of the drawings to the raised position shown in Fig. 3 (shown more in detail in Fig. 22), in which position the separator 8 has been moved into place adjacent to the front face of the plunger 5. It will be apparent, by referring to Figs. 3 and 22, that in the upward movement of the separator through the narrow groove 69, it is guided between the front face of the wall 77 and the adjacent wall in which are a number of guards or inset portions 68 of a height corresponding to the most elevated position of the pins 6, the guards being positioned opposite the pins 6. In the lower face of the plunger are grooves 502 serving to permit forward movement of the plunger over the guards 68 and the ends of the pins 6. When the separator has been raised to its elevated position in front of the face of the plunger between the plunger and the guide rails 80, the separator is moved along the face 60 onto the guide rails by the forward movement of the plunger, the separator remaining in contact thereafter with similar guide rails until the backing material has been cemented to the fibre sections and until the separators are removed in the part 96 of the apparatus (see Fig. 1).

It will be noted that the pins 6 have a portion 67 on one side thereof removed so that the portion of the face 60 upon which the separator rests will be of substantial width; if a portion of the circular pins were not thus removed, only a thin edge of the pins

would contact with the lower edge of the separator and the wear on the pins and separators would thus be excessive. Similarly, the front faces of the guide members 68 are preferably flat so as to present a broad surface of contact with the separators and with the adjacent front face of the pins 6, as will be apparent from Figs. 22 and 23 of the drawings.

The cutting of the fibre element material, such as a batt of loose fibres, preferably takes place while the material is firmly held both above and below the point of cutting so that after the cutting operation the severed section as well as the remaining batt portion are held under control, and the fibres of the severed section are rigidly held in place. By maintaining the plunger pressure against the severed section, which is preferably held between two separators, during and immediately after the cutting operation, no displacement or disturbance of the fibre arrangement in the severed section can take place.

Referring to Fig. 14 of the drawings, the cutting action is preferably accomplished by means of the passage of rollers 41 across the batt portion in contact with the knife edge 4 although obviously it would be possible to employ other cutting means than the specific form shown. As shown more particularly in Fig. 29, the cutting rollers 41 are mounted in the housing 418 on ball bearings 411 in order to reduce the friction and to permit rapid cutting of the fibre element material. A separate housing is preferably employed for each roller to permit separate adjustment or replacement of the cutting rollers. In the construction shown (see Fig. 14) there are five rollers mounted in housings 418 connected to the knife bar 42 and any roller in the series may be readily removed by unscrewing the set screws 427 connected therewith and moving the housing outwardly from the knife bar 42, whereby the spring members 426 will be released and the keys 429 maintaining the housings in alignment may be removed. The preferred mode of mounting the rollers in the housing is sufficiently illustrated by Figs. 29, 30 and 31 and need not be further described.

The knife bar 42, to which the housings carrying the cutting rollers are resiliently attached in the manner shown, is preferably adjustably mounted in a casting or plate 47, (see Figs. 2 and 14) to permit lateral movement of the rollers 41 across the adjacent portion of the batt 9 and knife edge 4. By means of the screws 428 the sliding fit of the knife bar 42 in the groove or way 470 (see Figs. 2, 14 and 28) may be adjusted.

The plate 47 preferably has two portions 471 extending from the main body of the casting 47 which are connected to the levers 44 by pin and slot connections 48, as shown more particularly in Fig. 2 of the drawings.

The levers 44 are preferably pivotally mounted on the pivot 45, being operated by means of cams 43 (see Figs. 2 and 5) through rollers 46 mounted at the end of the lower arms of the bell crank levers 44. By means of cams 43 of the form shown in the drawings and mounted with relation to the form and position of other cams as indicated in Fig. 5, the forward and return movement of the plate 47 and cutting rollers take place at required intervals to produce the cutting action, while the clamping jaws hold the batt section above the line of cutting, and the plunger 5 is in its intermediate position, holding the section of the batt below the knife edge against the mass of cut sections 91 and separators 8 at the entrance to the cut section chamber 92.

In order to produce the forward and return movement of the knife bar 42 and rollers 41 across the machine in contact with the knife edge 4, a pressure fluid cylinder 40 is employed, being mounted on rods 193, 194 (see Fig. 14) and a bracket or frame portion 195 (Fig. 16) connected to the frame 19; a valve 49, controlling admission and exhaust of pressure fluid to and from the cylinder, is preferably mounted adjacent to the cylinder on a bracket member 491 connected to the frame portion 195 (see Fig. 16). A pipe 402 connects the head end 403 of the cylinder with the valve 49, and a pipe 400 connects the valve with the crank end 401 of the cylinder. Connected to the valve 49 is a pressure fluid admission pipe 492 which is connected to any suitable source of pressure fluid supply, such as an air compressor, and a pipe 493, connected to the valve casing, serves to exhaust pressure fluid from one end of the cylinder 40 in the corresponding position of the valve.

In the form of valve shown there are two passageways 494 and 495, the valve being preferably operated by means of a valve rod 410. In the movement of the valve from head-end exhaust position (shown in Fig. 19) to head-end admission position (shown in Figs. 16, 17 and 18) the valve rod 410 is operated by means of a pin 406 which engages a pin 408 connected to one of the arms of the rod. The pin 406 is preferably mounted so as to move in a circular path, being preferably mounted on a cam 404 connected to the cam shaft 24, so as to be operated in timed relation to the movement of the cam shaft. After the pin 406 has moved over the end of the pin 408 in the rotation of the pin 406 around the axis of the shaft 24, the valve rod 410 is returned by means of the spring 412 into the head-end exhaust position, the valve rod moving against a stop 419 (see Fig. 16) to bring the passageways in the valve accurately into registration with the pipes, into the valve position shown in Fig. 19, corresponding to the dotted line position of the pin 408.

in Figs. 16 and 18 indicated by the numeral 408'.

In the position of the parts shown in Figs. 16 and 18 the head 496 is at the right, in which position the cutting rollers are at the extreme right of the machine as indicated in Fig. 15 of the drawings, the piston 497 being in the position indicated in dotted lines in Fig. 16. After the pin 408 and lever 410 are released through the movement of the pin 406 over the end of pin 408, the valve moves, as stated, into the position shown in section in Fig. 19, and pressure fluid is then exhausted from the head end 403 of the cylinder and admission to the crank end takes place simultaneously, but the piston 497 remains in the position indicated in Fig. 16 until the pawl 420, held by the shoulder 422 of the latch 414 is released through the further rotation of the cam 404 into the position in which the latch 414 drops over the shoulder 416 onto the lower surface 415 of the cam, whereby the head 496 moves to the left in Fig. 16 into the position indicated in dotted lines at 496'. In the further rotation of the cam 404 the latch 414 is gradually lifted into latching position, and as the pin 406 on the cam 404 moves the valve into intake position for the head end of the cylinder, the head 496 and parts connected therewith move to the right, and the pawl 420 moves over the shoulder 422 bringing the pawl to the right of the latch. As soon as the pin 406 moves over the end of the pin 408 bringing the valve into head end exhaust position, the end of the pawl 420 moves against shoulder 422 of the latch 414 and the cycle of operations above described is repeated. A spring 421 is preferably employed to positively move the pawl 420 downwardly over the shoulder 422 and a stop pin 423 is preferably employed in the position shown in Fig. 16 to limit the swing of the pawl around the pivot 424, the pin contacting with the forward face of the head 496 in predetermined limits of movement.

In the movement of the cutting rollers 41 and associated parts to the left, the rollers are in engagement with the batt at the knife edge 4, being brought into this position as indicated in Fig. 15 of the drawings, by the levers 44 operated by means of the cams 43 (see Fig. 2) in the manner heretofore described.

In order to permit the withdrawal of the cutting rollers 41 from contact with the knife edge 4 after the cutting stroke, so as to permit feeding of the batt between the cutting rollers 41 and knife edge 4, in the position shown in Fig. 2 of the drawings, a slot 499 (see Fig. 15) is provided in the head 496, which is rigidly connected to the piston rod 498, and a pin member 425, adapted to slide in the slot 499 is rigidly connected to the knife bar 42, whereby when the piston rod 498 is moved in

either direction, the knife bar 42 is constrained to move with it, and movements at right angles to the direction of movement of the piston rod may take place independently thereof within the limits permitted by the length of the slot 499.

The rotation of the cam shaft 24 is preferably accomplished by means of a pulley 240 (see Figs. 5 and 6) keyed to the cam shaft, 10 the pulley being driven by means of a belt from any suitable source of power, not shown. Connected to the shaft 24 on the opposite side of the machine is a sprocket 241 (see Fig. 4) which is connected by means of a chain 242 15 to a sprocket 243 keyed on the shaft 244 on which is mounted a gear 245 at the opposite side of the machine, which meshes with a change gear 246 which is adjustably mounted in position to be engaged or disengaged from 20 a gear 247, which is mounted on a shaft 248, upon the opposite side of which is mounted a spiral gear 249, which engages a spiral gear 923 on a shaft 924. On the shaft 924 are worms 925 and 926 which engage corresponding 25 worms 928 and 927 respectively (see Fig. 4) which are mounted on the same shafts as the rollers 938 and 937 respectively. One or more sprockets 937' are mounted on the same shaft as the roller 937, (see Fig. 6) 30 being keyed to the shaft so as to rotate with the corresponding roller. Chains 933' pass over the sprockets 937' to corresponding sprockets 935' mounted on the same shaft as the roller 935, whereby when the worm 926 is 35 driven through the rotation of the spiral gear 923, the worm wheel 927 is correspondingly driven and transmits rotation to the shaft on which the roller 937 is mounted, causing rotation of roller 937 and corresponding rotation 40 of the roller 935 through the chain drive as shown more particularly in Fig. 4 of the drawings.

In a corresponding manner the roller 938 is driven through the worm 925, which meshes 45 with the worm wheel 928, through the rotation of which a corresponding rotation of the roller 938, mounted on the same shaft as the worm wheel 928, takes place, the direction of rotation being indicated by an arrow in Fig. 50 4. The rotation of the worm wheel 928 causes rotation of the sprockets 938', which are mounted on the same shaft as the worm wheel 928 and roller 938, and through the chains 934' a corresponding rotation is transmitted to the sprockets 936' which are mounted on the same shaft as the roller 936. By 55 the rotation of the rollers 937, 935 and 938, 936 in the manner described, the belts 933 and 934 are moved in a direction such that the inner adjacent portions move toward the rear of the machine carrying with them, when the machine is operated, the cut sections of fibres in a manner more clearly indicated in 60 Fig. 1 of the drawings.

In a corresponding manner, the rollers in the sections 94 and 95 (see Fig. 1) may be similarly rotated either independently of the rollers in section 93 or geared thereto in any suitable manner.

Referring to Figs. 4, 26 and 27 of the drawings, pressure plates 931 and 932 may be mounted in any suitable manner in contact with the belts 933 and 934, being preferably mounted on the frame of the machine by means of bolts 197 passing through the openings 198 in the pressure plates. In order to vary the amount of pressure, a plurality of springs 199 are inserted in corresponding openings in the frame and in the pressure plate, as shown more particularly in Fig. 4 of the drawings, the nuts on the bolts 197 being screwed down to provide the desired pressure of the plates against the springs 199 and against the belts 933 and 934. The pressure plates 949 (see Fig. 1) in contact with the belts 945 and 946 are preferably mounted in a similar manner to that of pressure plates 931 and 932 as are also the platens 953 and 954 mounted on the belts 951 and 952 respectively, or these pressure plates and platens may be mounted in any suitable manner as will be apparent to those skilled in the art.

Operation

In describing the operation of the preferred form of my invention, the movements of the parts will be described with reference to the specific embodiment thereof shown in the drawings, but it will be understood that the machine or parts thereof may be so mounted that parts or movements which are described as being vertical or taking place vertically, may be horizontal or take place horizontally, and vice versa; and that positions of parts of the machine may be modified, as will be apparent to those skilled in the art without departing from the invention.

In the operation of the apparatus the pulley 240 on the shaft 24 (see Fig. 5) is driven from any suitable source of power, by means of which the various operating parts are actuated. The cams 51, operating the plunger 5, the cams 66 operating the separator lifting pins 6, the cams 33 operating to move the clamping jaw 3 toward and away from the material being fed, the cams 72 operating the cut-section holding pins 7, the cams 11 operating to move the jaw 1 toward and away from the pile element material being fed, and the cams 21 operating the jaw 2 in a direction longitudinally of the pile element material, are preferably all mounted on the same cam shaft 24 as shown in Fig. 5 of the drawings.

The sequence of operations which take place in the operation of the machine is as follows:

I. Feeding of batt

Assuming that the parts of the machine are in the position in which the feeding jaws 1

and 2 have gripped the batt or pile element material 9, as shown in Fig. 2, preparatory to the downward feeding movement, the first step consists in the vertical downward movement of the jaws 1 and 2, which may be traced in Fig. 11, through the clockwise rotation of the cams 21 into the position in which the rollers 22 thereon move toward the cam shaft or centers of rotation, i. e. from the elevated portion 210 to the lower surface portion 212, whereby the levers 23 pivoted at 15 are moved in a clockwise direction around the pivot 15 by means of the spring members 28. The connecting links 26 pivotally connected to the levers 23 through the pins 25, and pivotally attached to the casting 27 on which the holding jaw 2 is mounted, then move in a downward direction carrying the jaws 1 and 2 therewith, causing downward feeding of the batt.

The movement of jaw 1 horizontally will be hereinafter described under step XIII.

II. Feeding of separator

The second step in the operation of the machine involves the feeding of a separator 8 into place in front of the portion of the batt adjacent to the cut-section chamber 92.

The separator feeding step is accomplished by means of a series of rods or fingers 6 (see Fig. 7) which are preferably machined off on one side thereof to form a groove or flat side portion 67 at one side of the pins, and a broad surface or shoulder 60 at the top of the pins to engage a separator which is forced into place over the pins when it is in its lowered or retracted position. The means employed for bringing the separators into position for feeding comprises preferably a spring pressed feeding rod 85 (Fig. 2). Separator lifting pins or fingers 6 are preferably lifted or actuated by means of levers operated through cam motion, whereby the pins are operated to lift the separators into place in front of the plunger 5, between the lowered portion of the batt in front of the cut-section chamber and the face of the plunger.

Referring more particularly to Fig. 7, the upward movement of the pins 6 by which the separators are raised is preferably accomplished by means of cams 66 which raise rollers 61, shown in Fig. 7 in the raised position, thus moving the levers 62 in a counter clockwise direction around the pivot 15, resulting in raising the rollers 64 attached to the end of the levers 62 and lifting the casting or block 65 to which the pins 6 are attached. When the pins 6 are raised into the position shown in Fig. 3, a separator 8 is brought into position in front of the face of the plunger as illustrated therein.

The operation of advancing the plunger and the separator will now be described as step III.

III. Advancing of plunger to holding position

The step of advancing the plunger 5 from the position shown in Fig. 3 to that illustrated in Fig. 7, in which the face of the plunger is in substantially the same vertical plane as the knife edge 4, takes place through the movement of the cams 51, (see Fig. 11) having grooves therein which act on the rollers 52 mounted on the arms 55 of the bell-crank levers 54, pivoted on the pivot 45, the other arms 56 of the bell-crank levers 54 being connected to the plunger rod 57, thus causing reciprocating movement of the plunger 5 connected thereto. The plunger rod 57 is connected to the arms 56 of the bell-crank levers 54 by links 58 pivotally connected at 59 to the arms 56 permitting these ends of the arms to move in an arc and the plunger 5 to move in a horizontal plane in its guides 50.

It will be noted that in the forward movement of the plunger 5, the separator is first forced onto the guides 80 before the separator leaves the supporting shoulder 60 of the pins 6, as will be apparent from Fig. 3 of the drawings.

In the position of the plunger 5 in which it is in the vertical plane of the cutting edge 4, (see Fig. 7) the portion of the cam grooves with which the rollers 52 are in contact is an intermediate portion 512 located in position between the groove portions 514 and 516 of the cams, corresponding respectively to the extreme forward position of the plunger as shown in Fig. 9 in which the plunger is at the entrance to the cut section chamber, and the extreme retracted position, corresponding to the withdrawn or separator feeding position shown in Figs. 11 and 2. In the intermediate position therefore, as shown in Fig. 7, the portion of the cam grooves in contact with the rollers 52 is the groove portion 512 (see Fig. 11).

When the plunger is in the extreme forward position shown in Fig. 9, the corresponding portion of the cam grooves in contact with the rollers 52 is the portion 514 shown in contact in this view.

In the withdrawn position of the plunger 5 for the feeding of separators, as shown in Figs. 2 and 11, the portion of the cam grooves in contact with the rollers 52 is the portion 516 of the grooves shown in contact with one of the rollers 52 in Fig. 11.

In Fig. 7, the plunger is shown in its intermediate position for holding the batt 9 prior to cutting, and for the purpose of explaining the sequence of the steps following hereinafter in the operation of the machine, the plunger is now assumed to be in its intermediate position.

IV. Advancement of clamp jaw to batt holding position

Previous to the cutting operation in order

to satisfactorily accomplish the cutting, the batt is preferably held both above and below the point or line at which it is to be cut, as has been explained, the batt being held above the line of cutting during the cutting operation by means of clamp jaws 3 and 30, and below the line of cutting by means of the plunger 5 on one side of the batt which holds it against the mass of cut sections in the cut-section chamber 92, as illustrated in Fig. 8. In addition to holding the batt above the line of cutting during the cutting operation, the jaws 3 and 30 serve also to hold the batt while the feeding jaws 1 and 2 release their grip 15 on the batt and move upwardly to grip the batt at a more elevated point for feeding.

In the embodiment of the invention shown in the drawings, the holding clamp jaws 3 and 30 comprise a horizontally movable clamp 20 jaw 3 which may be advanced to clamp the batt against the stop plate or clamp jaw 30 gripping a portion of the batt between the clamp jaws adjacent to and substantially in the vertical plane of the knife edge 4 or 25 slightly to the rear thereof as illustrated in Figs. 7 and 8.

The movement of the clamp jaw 3 inwardly preferably takes place simultaneously with the movement of the plunger 5 toward the cut-section chamber 92 into its intermediate position, this movement being caused by the corresponding movement of the associated operating cams, operating through rollers to levers suitably pivoted to obtain the desired 35 movement.

The stop plate or clamp jaw 30 is preferably pivoted at its top or upper end to a pivot 32, illustrated in Fig. 2, and is forced outwardly toward clamp 3 by means of suitable spring members 304, whereby the batt is guided in its downward movement out beyond the knife edge 4, so as to prevent the latter from interfering with the batt feed. When the clamp jaw 3 is brought forwardly 45 toward the clamp jaw 30 through the movement of cams 33 into the position shown in Fig. 9, the batt is tightly held between the jaws.

Referring to Fig. 9, the movement of the clamp jaw 3 inwardly to grip the batt between it and clamp 30 takes place when the cams 33 have moved into a position to permit the rollers 34 to move toward the center of the cams, or in other words to descend upon the lower surface 331 of the cams 33 as shown the bell-crank levers 36 being then moved correspondingly in a clockwise rotation about the pivot 15 whereby the links 37, pivoted to the arms 35 of levers 36 at the pivots 38, (see Fig. 9) are forced inwardly, causing the clamp jaw 3, to which they are in turn connected through pivots 39, to move forwardly into clamping position. It is to be understood that the position of the plunger 5 and the associated parts as illustrated in

Fig. 9 is that assumed immediately after the cutting operation, after the plunger has been advanced to its forward position to insert the last cut-section into the cut-section chamber, although the clamp 3 and the operating levers associated therewith are in the same position that they are in immediately preceding the cutting operation. The relative position of the holding and cutting elements immediately preceding the cutting operation is clearly illustrated in Fig. 8.

V. Advancement of cutting rollers into position for cutting

Before the step of cutting the batt takes place, the cutting rollers 41 are moved into position in contact with the batt for pinching off or cutting the batt between the rollers and the knife edge 4 (see Fig. 8), the rollers 41 being brought into and out of engagement 80 with the cutting edge 4 by means of cams 43 mounted on the shaft 24, and the levers 44 pivoted at 45 and having rollers 46 thereon to engage with the surfaces of the cams, thus operating the levers 44 and the plate 47 attached thereto to bring the rollers in and out of contact with the batt on the cutting edge. The frame or knife bar 42 in which the rollers 41 are resiliently mounted slides in guides 470 in the casting or plate 47 and is provided with 85 adjusting screws 428 to permit adjusting the sliding fit of the frame 42 in the guides, as 90 has heretofore been described.

VI. Removal of retaining pins holding cut sections in the cut section chamber

Before the cutting of the batt takes place, the holding pins 7 which are mounted in the pin bar 71 (see Fig. 7) are withdrawn from the position shown in Fig. 7, designated as the raised position, to the position shown in Fig. 8, referred to as the lowered position, which is accomplished by means of cams 72, which operate levers 73 through rollers 75 connected to the levers 73, whereby pin bar 71 mounted adjacent one end of the levers 73 is operated. The pin bar 71 is preferably operated by the levers through rollers 74, adapted to operate in slots 78, (see Fig. 12) the rollers being mounted upon the ends of levers 73 in such a 105 manner that the axes of the rollers extend in the longitudinal direction of the levers 73, thus permitting the movement of the pin bar 71 on the diagonal to bring the pins 7 through the orifices 76 in the plate 77, at the entrance 110 end of the cut-section chamber into their raised position (see Fig. 12). By means of rollers 74, riding in slots 78 in the pin bar 71, diagonal movement during the raising and lowering of the pin bar 71 may be accomplished without excessive friction between the 115 relatively moving parts.

The relative position of the parts shown in Fig. 8 is that assumed immediately prior to the cutting operation, the batt being clamped 120

above the knife edge 4 between the clamps or jaws 3 and 30; and at the knife edge between the rolls 41, and the knife edge 4; and below the knife edge between two separators, which tightly clamp the corresponding portion of the batt, one separator being held in pressure contact with the batt by means of the plunger and the other being forced into pressure contact with the batt by means of the back pressure of the cut sections in the cut-section chamber 92. In this position, therefore, the batt is tightly held in place during the cutting operation to permit cutting without disarranging the fibres; and the parts are so held that after the cutting has taken place the severed portion of the batt is still rigidly maintained in position, so that no local disturbance of the fibres takes place with relation to the remaining body portion of the fibres in the cut-section chamber.

VII. The cutting operation

The cutting operation by means of which a section is severed or separated from the remainder of the batt consists in passing the rollers 41 rapidly over the portion of the batt adjacent to the knife edge 4. The movement of the rollers over the knife edge is preferably accomplished by means of compressed air in a cylinder 40, the operation of which is controlled by means of an operating valve 49.

The operation of the air valve 49 is controlled by means of a pin 406 mounted on a part 404 connected to the cam shaft 24, (see Figs. 16 and 18) which engages a corresponding pin 408 positioned at one end of the valve operating rod 410, by means of which the valve is brought from the head end exhaust position into the head end intake position. The cam or part 404 is rotated on the cam shaft 24 in the direction indicated by the arrow in Fig. 18, and after the pin 406 has been brought down into the position shown more particularly in Fig. 16, admission of compressed air takes place into the head end 403 of the cylinder 40 and exhaust takes place simultaneously from the crank end 401 of the cylinder as indicated by arrows in Fig. 17, which shows the relative positions of the valve and valve ports. By the admission of compressed air to the head end of the cylinder 40, the piston therein together with the cutting rollers and other parts connected therewith are returned or brought across the machine into position for the cutting stroke, the pawl 420 being thereby brought to the right of the shoulder 422 on the latch 414 into the position indicated in Fig. 16. As the cam 404 continues to rotate in the direction of the arrow in Fig. 18, the pin 406 slides over the end of pin 408, thereby releasing the lever 410 which is returned into head and exhaust position by means of the spring 412. The reversal of

the position of the valve 49 causes admission of air to the crank end of the cylinder in addition to connecting the head end with the exhaust, and produces a slight movement of the head 496 to the left, in Fig. 16, so that the pawl 420 engages the shoulder 422 on the latch 414, whereby as soon as the pawl 420 is released by the latch 414 caused by the further movement of the cam 404 to the position in which the latch 414 drops over the shoulder 416 to the portion 415 of the cam, the rollers 41 and parts associated therewith will move to the left to perform the cutting stroke. The position of the cam 404 is so adjusted in the operation of the machine that the latch 414 is on the high side of the cam when the position of the valve is reversed, immediately preceding the drop over the shoulder 416 to the low portion 415 of the cam surface. During the time that the pawl 420 is engaged by the shoulder 422, the air pressure is built up in the crank end 401 of the cylinder 40, so that as soon as the latch 414 is released through its movement over the drop 416, the pawl 420 is released together with the cutting rollers and associated parts, and a rapid movement of the piston and cutting rollers toward the head end 403 takes place. Before the cutting stroke occurs, the rollers 41 are brought, by means of the cams 43 and parts connected therewith as heretofore described, from the position shown in Fig. 14 into engagement with the knife edge 4, as shown in Fig. 15.

Assuming the parts to be in the position in which the rollers and corresponding parts have been moved to perform the cutting stroke, the succeeding step involves the advancing of the plunger to force the severed batt section into the cut section chamber, as will now be described.

VIII. Advancing of plunger to insert the last cut section into the cut-section chamber

The next step in the operation comprises the advancement of the plunger 5 by means of its cams and levers to force the cut section of the batt into the cut-section chamber, the plunger being advanced beyond the point or vertical plane at which the pins 7 are located, as will be apparent from Fig. 9 of the drawings. Referring now to Fig. 11 of the drawings, the portion of the grooves of the cams 51 which must contact with the rollers 52 to advance the plunger 5 to its most advanced position, is that indicated by 514. By periodically advancing the plunger in the manner described, the cut sections are fed forwardly in the chamber 92 as the additional sections are inserted one by one into the forward end of the chamber in the manner indicated, the sections being retained under pressure by means of the back

pressure of the pressure belts 933 and 934 and by the pressure of the plunger 5 during the period in which it is in contact with the sections in its most advanced position or 6 of the pins 7 during the time they serve to hold the sections in the cut-section chamber. When the plunger is advanced into its extreme forward position after the cutting operation the pins 7 are obviously in their with- 10 drawn or lowered position.

IX. Returning of retaining pins into raised position

The next step in the operation of the ma- 15 chine involves replacing the plunger in front of the cut-section chamber by suitable holding or supporting means for the cut sections in the chamber 92 to permit withdrawal of the plunger into its retracted position (in 20 which the feeding of a separator in front of the plunger takes place), without disturbing or causing disarrangement of the cut sections in the chamber.

In the embodiment of the invention shown, 25 a series of pins 7 are mounted in a diagonal direction upon a pin bar 71, the pin bar being mounted in guides 70 to permit diagonal movement into the raised and lowered position, whereby the pins 7 will be correspondingly inserted or withdrawn through openings 76 in the floor of the cut-section chamber, the openings 76 communicating with the space at the forward end of the plunger in its advanced position. In the plunger are 30 a series of grooves or slots 53 extending inwardly from the end or face of the plunger in a diagonal direction corresponding to the inclination of the pins 7, so that when these pins are raised in the advanced position of 40 the plunger and inserted into the slots, the plunger may be withdrawn without necessitating movement of the pins, thus leaving the pins in position at the entrance to the cut-section chamber so as to hold the cut 45 sections therein. In other words, when the plunger is withdrawn from the position shown in Fig. 10 into the position shown in Fig. 2, the pins in their raised position serve 50 to prevent the cut sections 91 in the cut-section chamber 92 from moving forward into the path of the batt and serve also to maintain the cut sections in contact with each other and prevent disturbance of the fibres 55 in the arranged sections.

X. Opening and raising of holding jaws

While the plunger 5 is being moved forward toward the rear end of the machine into 60 the position shown in Fig. 9, and while the batt 9 is still being held above the cutting edge 4 by means of the clamp jaws 3 and 30, as shown in this figure, the feeding jaws 1 and 2 are opened and raised in position in 65 readiness to obtain a new grip on the batt

at a more elevated or advanced position for feeding. The distance traversed by the feeding jaws 1 and 2 in their movement to obtain the new grip is necessarily equal to the height of a cut section 91, assuming that 70 there is no stretching or elongation taking place in the batt during the feeding operation.

The preparatory movement of the jaws 1 and 2 is obtained, in the embodiment shown, 75 by means of a cam and lever action. When the rollers 12 (see Fig. 2) are brought through the rotation of the cams 11 onto the elevated portion of the cam surface designated by the numeral 118, the arms 13 are 80 rotated around the pivot 15 in a counter clockwise direction, giving the arm 17 a corresponding movement, whereby the block 18, which is connected to the arm 17 through the pin and slot connection 16, is moved in its 85 guides 182 (see Fig. 5) in a direction away from the jaw 2, whereby the jaw 1, which is connected to the block 18, is separated from jaw 2.

In the movement of the block 18 in a direction away from the jaw 2, the springs 140, held by the rods 14 (see Fig. 5) are compressed by contact with lugs 180 mounted on the block 18 which move forward toward the outer ends of the rods, thus causing compression of the springs. The springs 140 permit the use of different thicknesses of batt, by permitting automatic adjustment in the clamping of the batt by the feeding jaws. 95

The upward movement of the jaw 2 bringing with it the jaw 1, is effected through cam action by means of the cams 21 (see Fig. 11) which act upon the rollers 22 connected to the levers 23 connected by means of pivotal connections to arms 26, the upper 100 ends of which are connected to a block member 27 which is connected to the jaw 2 which in the embodiment shown is movable only in a vertical direction. When the arms 26 and jaw 2, connected thereto, are moved upwardly, the springs 28, connected to the lower end of the arms 26, are put under tension tending to pull the arms downwardly, whereby when the cams 21 have moved into a position permitting the return or downward movement of the jaws 1 and 2, the parts will be positively returned by means of the spring members. The jaws are preferably interconnected so that the movement of jaw 2 upwardly carries with it the jaw 1 (see Fig. 2) 110 which is accomplished in the preferred form of the invention by means of a sliding pin connection as heretofore described.

The movement of the jaws upwardly into 115 position to grip the batt at an advanced point for feeding may take place any time after the clamp jaw 3 has been advanced against the plate or clamp jaw 30, which is accomplished by operation No. IV. 120 130

XI. Return of separator feeding pins into separator feeding position

The withdrawal or return of the separator feeding pins 6 from the raised position, shown in Fig. 7, into the lowered position for feeding shown in Fig. 9, may take place at any time following the advancing of the plunger to the holding position referred to above as operation No. III. The return of the feed pins may, if desired, take place simultaneously with steps VIII, IX and X above described, or may be designed to occur immediately before a separator is required, thus moving downwardly and returning with a separator just before the plunger moves forward into the intermediate position. In the preferred form of the mechanism, however, the cams 66 (see Fig. 7) are so designed and set with respect to the other cams that the separator feed pins 6 are gradually returned into their withdrawn position immediately after the retaining pins 7 have been withdrawn to their lowered position. The point at which the return or downward movement of pins 6 occurs will be dependent upon the form and set or adjustment of the cams 66 shown in Fig. 7, the cams being preferably of the box type, whereby the levers controlled by the cams are positively actuated. The pins 6 are shown in Fig. 9 in their lowered position ready for feeding a separator plate, and in Fig. 2 in an intermediate raising position in which the feeding of a separator plate is taking place.

XII. Reclamping of batt

While the batt is still held by the clamp jaws 3 and 30 after the cutting operation, the jaws 1 and 2 are moved up as has been described under operation No. X above, and are now made to grip the batt preparatory to feeding it downwardly for the cutting of a new section. In the embodiment of the invention shown, this is accomplished by the use of a jaw 2 which is movable only in a vertical direction, being attached to a portion which is guided in its movement by means of guides as heretofore described. As the jaw 2 is raised by means of the cams 21 and the levers 23 and 26, (see Fig. 11), the jaw 1, which is connected thereto through the pins 200 and slots 100, moves upwardly therewith and the jaws are then brought together. The movement bringing the jaws together is preferably accomplished through the horizontal movement of the jaw member 1 through the clockwise rotation of the arms 13 (see Fig. 2), acted upon by the cams 11 through the rollers 12 which pass over the shoulders 115 onto the lower portion 114 of the cams. By the downward movement of the arms 13 around the pivot 15, the arm 17 (see Fig. 2) moves in a clockwise direction, or inwardly with the casting 18, whereby the jaw 1 is caused to slide inwardly or to the right on the pin

200 causing the jaws 1 and 2, or the jaw members 10 and 20, to grip the batt. One or more springs 140 force the rollers 12 into contact with the surfaces of the cams 11 thereby serving to control the inward movement of the jaw 1 and results in resilient contact of the jaw 1 with the batt, permitting the machine to be used on different thicknesses of batt. In the embodiment shown, for example, if a batt were employed of twice the normal thickness, the rollers 12 would be raised slightly off the lower surface 114 of the cams in the position shown in Fig. 2, but the operation would otherwise remain the same as with ordinary thicknesses of batt. Obviously the parts may be so designed that the rollers 12 will be continuously in contact with the surface of the cams or in contact therewith except when adjacent the lowermost surface 114 thereof as explained. After the batt has been gripped by the jaws 1 and 2, the lower clamp jaws 3 and 30 are released in the manner hereinafter described.

The next steps in the operation of the machine include the return of the plunger to its initial or withdrawn position, the return of the knife bar to its initial position and the withdrawal of the clamp jaw 3 from its engaging position. These steps are preferably made to occur substantially simultaneously, although they may be obviously made to occur at any suitable time and in any sequence, provided they occur before the batt is fed downwardly by the jaws 1 and 2. These steps will now be described as occurring simultaneously.

XIII. Return of plunger to initial position

The plunger 5 is shown in its initial position in Fig. 2, in which position a separator may be fed in front of the plunger. The return of the plunger to this position occurs when the rollers 52 move from the sections 514 of the grooves 510 of cams 51, as illustrated in Fig. 9, (corresponding to the most advanced position of the plunger), to the outer groove portions 516 of the cams, this position being illustrated in Fig. 11, in which position the plunger is in its initial or withdrawn position; the plunger remains in the position shown in Fig. 11 until in the rotation of the cams 51 the rollers 52 move again to the groove portions 512 of the cams, corresponding to the intermediate position of the plunger. The cams 51 are preferably designed to operate so that the movement of the rollers 52 from the groove portions 516 into the groove portions 512 will not occur until after a separator has been inserted in front of the plunger by the corresponding movement of the separator feed pins 6 heretofore described.

XIV. Return of knife bar and cutting rollers to initial position

The return of the knife bar 42 and rollers

- 41 to the position away from the batt is accomplished, as will be apparent from Fig. 2, by the movement of the rollers 46 from the elevated surface 431 of the cams 43 to the lower surface 432 thereof, thereby moving bell crank levers 44 about the pivot 45 in a counter clockwise direction, and thereby moving the knife bar holding plate 47, attached thereto through the pin and slot connections 10 48, in a corresponding direction, by which the knife bar and cutting rollers are moved away from the cutting edge 4.

After the movement of the knife bar away from the batt has taken place, the knife bar 15 with its rollers is returned transversely across the machine to the right from the position shown in Fig. 14 to the opposite side of the machine. It is obvious that instead of moving the knife bar transversely after the movement thereof away from the batt, it may be moved transversely simultaneously therewith, although the movement in sequence is preferred. This movement is preferably accomplished by the valve and air cylinder 20 mechanism, heretofore described, by the admission of air into the head end 403 of the cylinder 40 (see Fig. 16) bringing the rollers 25 41 from the position shown in Fig. 14 to the right, whereby when the rollers are again moved in contact with the knife edge as shown 30 in Fig. 15, they are in position for another cutting operation.

*XV. Withdrawal of clamp jaws from clamp-
ing position*

Before the jaws 1 and 2 can operate to feed the batt into cutting position, the clamp jaws 3 and 30 must be moved out of clamping position, but it is to be understood that the clamp 40 jaws may be disengaged at any time after the jaws 1 and 2 have moved into engagement with the batt and after the cutting operation has been completed. In order to move the clamping jaw 3 in and out of clamping 45 position, cam actuation shown more particularly in Fig. 9 and heretofore described is preferably used.

The above described movement of the clamp jaws completes the cycle of operations, 50 the cycle being obviously repeated for each section of batt 91 which is cut and fed into the batt cut-section chamber 92.

The separators 8 are preferably introduced into the machine in magazines 81 (see Figs. 20 55 and 21) which are made removable from the machine so as to permit being filled with separators independently of the machine. The recess or chamber 82 into which the magazine is introduced is preferably located directly 60 under the plate 83, the top of which is level with the bottom of the cut-section chamber 92 and on which the plunger 5 slides, whereby the separators may be readily fed into place in front of the plunger to be fed into 65 contact with the batt portion to be cut.

After the magazine has been introduced into place, the spring units 84 are connected in place in front of the magazine chamber 82, so that the pins 85 therein pass through the openings 86 in a wall 87 of the magazine chamber 82 and maintain a pressure on the separators during the separator-feeding operation.

It will be understood that the product, method and apparatus which have been described may be modified as will be apparent to those skilled in the art without departing from the spirit or scope of the invention as defined in the claims.

The method of forming the product involving the use of separators as described, constitutes the preferred method of making my product, but I contemplate modifying the method for certain purposes by the omission of separators in the operation of the machine described. If a product having a maximum pile density is to be formed, for example, the operation of the machine may be readily modified to carry out the method steps without the use of separators, the parts of the machine for feeding and handling of separators being rendered inactive or disconnected; obviously also a machine embodying the features of my invention might be made without the inclusion of parts for operating with the use of separators.

It will be apparent also that the cutting mechanism and mode of operation thereof might readily be modified in any desired manner to vary the cutting operation. The apparatus might, for example, be modified to produce a cutting stroke on both the forward and return stroke of the cutting rollers instead of cutting only on the stroke to the left with reference to Fig. 16 of the drawings. In order to accomplish this, however, it would be necessary to provide two cams for releasing the cutting mechanism, similar to the cam 404, for example, but mounted on a shaft independent of the main cam shaft 24 and driven at one-half the speed of the main cam shaft in order to produce operation of the parts of the mechanism in the desired sequence. In this case, obviously the cams would be mounted in operative relation to latching devices similar to latch 414 and 420 and located preferably at the extreme ends of the stroke of the head 496. It would also be necessary to produce operation of the control valve 49 in timed relation to the operation of the cam shaft 24 in the same manner as occurs in the preferred embodiment of the invention described, and, in modifying the cutting mechanism to produce a cutting stroke at both the forward and return stroke of the cutting rollers, a disc might be mounted in the position of the cam 404 on the main cam shaft 24, an engaging part such as a pin 406, for example, being mounted on the disc

serving to reverse the position of the valve 120 125 130

for the control of admission and exhaust of pressure fluid to the cylinder 40. Other portions of the apparatus might readily also be modified by the use of means, or by the substitution of equivalents, well known in the art.

In the preferred embodiment of the invention as has been described, the cams 11, 21, 33, 43, 51 and 72 are preferably mounted in pairs on the same cam shaft 24 but obviously, the operation might be obtained with single cams if desired, or more than two cams might obviously be employed to perform the function or effect the operation described, and obviously the various cams might be mounted if desired on separate shafts, or two or more cams might be mounted upon one shaft to obtain the desired operation. I do not desire, therefore, to be limited to the mode of mounting described and illustrated, nor to the specific form of the cams disclosed herein.

It will be apparent also, that the feeding of the batt or pile element material might be modified to accomplish the same result above described. In the embodiment of the invention shown in the drawings, for example, the guide member 29 confines the movement of the jaw 2 to a vertical direction whereas the jaw 1 moves in both a horizontal and vertical direction; but it will be apparent that means could be provided to move the jaw 2 both horizontally and vertically, thereby providing the movement of the jaws out of contact with the batt and again bringing the jaws into contact therewith by a movement having a horizontal component. The clamping jaws 3 and 30 might also be modified to both operate in a similar manner as for example by operating the jaw 30 in the same manner as that described in connection with the jaw 3, but in modifying the operation of the clamp jaw 30 in this manner, it would be preferable to also modify the cutting mechanism by the use of a movable knife edge 4 which might be retracted or withdrawn during the downward feeding of the batt, so as not to interfere with the feeding operation. It will be apparent also that the mode of operation might readily be modified so that the movement of parts which take place horizontally would take place vertically and vice versa; for example, the applying of rubber cement and backing elements to the fibre material, which has been described in connection with Fig. 1 as taking place in a horizontal direction, might obviously be modified to take place vertically; and obviously the cutting operation as illustrated at 97, could also be made to take place vertically as will be apparent without further description.

It is to be understood also, that I may employ any suitable form of pile element material although it is preferable to employ

a batt as has been described. The apparatus is equally operative, however, with yarn or other forms of spun or twisted fibres.

Having thus described my invention, what I claim is:

1. A method for the continuous production of pile fabric which comprises passing upstanding fibres into an enclosed space to form a compact, confined mass in which the fibre ends are exposed in opposite faces thereof, the adjacent walls of the said enclosed space serving to guide the said fibres in controlled relative position into contact with a backing material, subjecting the mass to a substantial pressure longitudinally of the mass to provide the desired density therein, and cementing the fibre ends exposed in one of the said faces to said backing material while the fibres are maintained under the said pressure. 70 75 80 85

2. A method for the continuous production of pile fabric which comprises feeding a mass of upstanding fibres into an enclosed space in which the fibre ends are maintained in contacting relation with the adjacent opposite walls thereof, passing a flexible backing material into one portion of the said enclosed space into contact with the fibre ends at one face of the said mass, subjecting the fibre mass in the enclosed space to a substantial pressure longitudinally thereof and cementing said flexible backing to the adjacent fibre ends while the fibre mass is maintained under the said pressure. 90 95 100 105

3. A method for the continuous production of pile fabric which comprises passing fibres in a longitudinal direction into an enclosed space having horizontal and vertical adjoining walls, to form a forwardly moving compact confined mass in which the fibres are arranged transversely of the mass so as to form continuous surfaces in contact with the opposite horizontal walls of the enclosed space, guiding the said fibres in controlled relative position into contact with a backing material, subjecting the said fibre mass to pressure longitudinally of said mass and cementing the said backing material to one of said continuous surfaces while the fibres are maintained under the said pressure. 110 115 120 125

4. A method of making a pile fabric which comprises feeding a mass of upstanding fibres through an enclosed space in contacting relation with the upper and lower walls of said space, applying back pressure to the fibre mass during the passage through said space to compact the fibres to the desired density, and cementing the ends of said fibres on one face of the said mass to a backing material while the fibres are maintained under pressure to form a pile fabric product of uniform density. 130 135

5. A method of making a pile fabric which comprises feeding a mass of fibres in substantially parallel relation through an enclosed space in contacting relation with the upper and lower walls of said space to form con-

- tinuous surfaces between which substantially parallel fibres run, applying pressure to the fibre mass longitudinally thereof during the passage through said space to compact the fibres to the desired density, and cementing a backing material to one of said continuous surfaces while the fibres are maintained under said pressure to form a pile fabric product of uniform density.
6. A method for the continuous production of pile fabric which comprises cutting fibre elements from a body of fibre material while the fibre elements are clamped to prevent displacement of the fibres during the cutting operation, forming a uniformly moving mass of clamped fibre elements maintained longitudinally under pressure and continuously cementing an advancing strip of backing material to the fibre ends of the said moving mass while the said elements are held in clamped relation.
7. A method for the continuous production of pile fabric which comprises cutting fibre elements from a body of fibrous material while the portion to be severed is rigidly held in position to prevent displacement of the fibre elements, assembling the cut fibre elements into a mass of upstanding fibres, moving the said mass forwardly into contact with a strip of backing material to be attached to the severed fibres, and cementing the fibre elements to the backing while the fibres are rigidly held in position to form a continuous strip of pile fabric.
8. A method of making a pile fabric which comprises cutting fibre elements from a body of fibrous material while the portion to be severed is rigidly held in position and forming a mass of rigidly held fibres having their ends exposed, feeding forward a strip of backing material to be attached to the end of the severed fibres, and cementing the ends of the fibre elements to the backing by means of a rubber cement and vulcanizing the cement while the fibres are held in clamped position to prevent relative displacement thereof, thus forming a continuous strip of pile fabric.
9. A method for the continuous production of pile fabric which comprises passing a mass of upstanding fibres while maintained in fixed relative position by lateral pressure through an enclosed space, continuously feeding a strip of backing material over a support into the enclosed space in contact with the exposed ends of the fibres on one side of the mass and progressively securing said fibres to the said strip in the said enclosed space to form a continuous strip of pile fabric.
10. A method for the continuous manufacture of a pile fabric which comprises passing sections of upstanding fibres into an enclosed space to form a continuously moving aligned fibre mass, holding the said sections substantially independently in the said mass, feeding forward a strip of backing material over a support into the enclosed space and securing the said fibres to said strip by a cementing medium to form a continuous strip of pile fabric.
11. A method for the continuous manufacture of a pile fabric which comprises passing into an enclosed space upstanding fibres controllably held in position so that the ends of the fibres project into contact with the opposite walls of the said space, feeding forward a strip of backing material over a support into a portion of said enclosed space into contact with the fibre ends, cementing the fibre ends to said strip by means of a vulcanizable cement, and thereafter vulcanizing the said cement to permanently attach the fibres to the said backing.
12. A method of making a pile fabric which comprises feeding under pressure a mass of upstanding fibres held between guided separators into an enclosed space in contacting relation with opposite enclosing walls, covering one face of said mass containing fibre ends with a vulcanizable cement material, passing a flexible backing material into contact with the coated face of the fibres, exerting pressure on the backing material to bring it into pressure contact with said coated face and vulcanizing the said cement material while the said backing material is held in pressure contact with said coated face.
13. A method of making a pile fabric which comprises cutting sections from a pile element forming material while the portion to be severed is controllably held by clamping means, passing the severed portion while still controllably held into a chamber, to form a fibre mass, feeding forward a strip of backing material and securing the said fibres to the said strip by means of a cementing material to form a continuous strip of pile fabric.
14. A method of making a pile fabric which comprises cutting sections of a pile element forming material while the portions to be severed are clamped between separators, arranging the severed sections side by side in a chamber to form a mass of upstanding fibres and to present the ends of the fibres in two parallel planes, feeding a strip of backing material into contact with the exposed ends of the fibres in one of said planes, and securing the backing material thereto by means of an adhesive material to form a continuous strip of pile fabric.
15. A method for the continuous production of pile fabric which comprises cutting sections crosswise from a pile element material while the portions to be severed are maintained clamped between the clamping elements serving to rigidly hold the fibres in the sections in fixed position relative to each other continuously, feeding the severed sections forwardly through an enclosed space

while the fibres are held clamped between the said elements to form a packed mass of upstanding fibres therein, feeding a strip of backing material into contact with the said fibres in a portion of the said enclosed space, and permanently securing the ends of the said fibres to the said strip to form a continuous strip of pile fabric.

16. A method of making a pile fabric which comprises feeding a pile element material into place to be clamped in position, applying holding means comprising separators to a portion of pile element material to be severed, cutting sections crosswise from the pile element material while the portions to be severed are held in place between the separators, conveying the severed sections while maintained in place between the separators into contact with a strip of backing material, securing the said sections to the backing material while held in place between the separators to form a strip of pile fabric and removing the said separators.

17. A method for the continuous production of pile fabric which comprises feeding a pile element material to be cut, engaging the portion of the pile element material to be severed with holding means to rigidly clamp the fibres during the cutting operation, cutting the section to be severed beyond the portion engaged by said holding means, assembling the cut sections into a uniformly moving mass, feeding a strip of backing material into contact with the fibres of said moving mass and permanently securing the ends of the fibres to the said strip to form a continuous strip of pile fabric.

18. A method of making a pile fabric which comprises feeding a pile element material to be cut, engaging a portion thereof to be severed with separators held in pressure contact therewith, severing the said portion, passing the severed portion into pressure contact with a mass of upstanding sections of material previously severed, and maintaining pressure thereon to attain the desired pile density of the mass, passing the severed sections into contact with a backing material and securing the said sections to the backing material by means of a cement to form a strip of pile fabric.

19. A method of making a pile fabric which comprises feeding a pile element material to be cut, engaging the portion to be severed between separators having a less width than the sections to be severed, cutting the pile element material crosswise at a point beyond the said separators, passing the severed section together with the separators into an enclosed space to form a mass of fibres in which the ends of the fibres lie in substantially parallel planes, maintaining pressure on the mass of cut sections, combining the fibres on both sides of the mass with strips of backing material by means of a cement ma-

terial applied to the backing and the adjacent ends of the fibres, and slitting the fibres in a plane between the backings to form two separate pile products.

20. A method of making a cemented pile fabric which comprises cutting a pile element material rigidly held above and below the point of cutting to prevent the disturbance of the fibres in the cut sections and in the remaining pile element material, transferring the cut sections into contact with a backing member and cementing the cut sections to the said backing member while the pile element material is still rigidly held to prevent displacement of the fibres until the fibres are permanently cemented to the said backing member.

21. A method of making a cemented pile fabric which comprises cutting a pile element material while rigidly held both above and below the point of cutting to prevent displacement of the fibres in the cut section, transferring the cut section under pressure into a space to form a mass of fibres having a high pile density, and cementing a backing material to the fibres while held under said pressure to form a pile fabric product having the desired density.

22. A method of manufacturing a cemented pile fabric which comprises feeding a batt in a longitudinal direction, cutting sections of the batt at right angles to the longitudinal direction while holding the batt at both sides of the point of cutting to prevent disturbance of the fibres by the cutting action, transferring the cut sections thereof into contact with a backing member, and cementing the pile element material to the said backing member.

23. A method of manufacturing a cemented pile fabric which comprises cutting a batt into sections while the portions to be severed are rigidly held in place to prevent relative displacement of the fibres, transferring the cut sections into a space so as to expose the fibre ends thereof in two plane surfaces, the fibres being maintained substantially at right angles to the said surfaces, and cementing a flexible backing member to at least one of said surfaces to provide a cemented pile fabric product.

24. A method of manufacturing cemented pile fabric material which comprises feeding a batt in a longitudinal direction, cutting sections of the batt at right angles to the longitudinal direction of feed while rigidly holding the batt both above and below the point of cutting, thereafter transferring the cut sections to a chamber to form a fibre mass in which the pile elements are arranged at substantially right angles to the exposed surfaces thereof containing the fibre ends, maintaining the fibre mass under lateral pressure to produce a high pile density in the mass and to prevent disturbance of the fibre

elements therein, and thereafter permanently cementing a flexible backing material to a surface of the fibre mass containing the fibre ends while the fibre elements are maintained under the said pressure to obtain a product having a high pile density.

25. A method of manufacturing a cemented pile fabric which comprises intermittently feeding a mass of pile element material into a position to be cut by a cutting means, clamping the pile element material on each side of the said cutting means, cutting the pile element material by means of said cutting means, transferring the cut sections, while maintained under control to prevent disturbance of the fibres, into a space in which the fibre elements are maintained at substantially right angles to the opposite exposed surfaces of the mass containing the fibre ends, applying a vulcanizable cement to a surface of the fibre mass containing the fibre ends, passing a flexible backing material into contact with said coated surface of the fibre mass, and vulcanizing the said cement to permanently attach the fibre elements to the said backing.

26. A method of manufacturing a cemented pile fabric which comprises intermittently feeding a mass of pile element material into a position to be cut by a cutting means, clamping the pile element material on each side of the said cutting means, thereafter cutting the pile element material with said cutting means, transferring the cut sections, while maintained under control to prevent disturbance of the fibres, into a space in which the fibre elements are maintained at substantially right angles to the opposite exposed surfaces of the mass of fibres thereafter applying a vulcanizable cement to the opposite exposed surfaces of the fibre mass, cementing a backing material to each side of the coated fibre elements, and thereafter cutting the fibre elements in a plane between the parallel backing members to provide two separate pile fabric products.

27. A method of manufacturing a cemented pile fabric which comprises cutting pile element material from a mass of fibres while rigidly holding said material above and below the point of cutting, maintaining a pressure contact on the severed material, passing the severed material into a chamber to unite with a mass of upstanding cut elements in which the fibre ends are exposed at opposite surfaces of the fibre mass, whereby the fibre elements are arranged substantially at right angles to the exposed surfaces of the mass, applying a cement material to each of the exposed surfaces of the mass while under said pressure, and cementing a backing material to each of the exposed coated surfaces, and cutting the fibre mass in a plane between the backing members to provide two separate pile fabric products.

28. A method for the manufacture of cemented pile fabric material which comprises intermittently feeding a pile element material into cutting position with respect to a cutting means, rigidly holding the said element material on one side of the cutting means by clamping means and on the other side of said cutting means between separators during the cutting operation, thereafter cutting the pile element material crosswise of the said material, passing the severed sections maintained between separators into a chamber so as to form alternating severed sections and separators therein, and permanently applying a backing material to an exposed surface of the pile element material while the said material is maintained under pressure.

29. A method for the manufacture of cemented pile fabric material which comprises intermittently feeding a pile element material into cutting position with respect to a cutting means, rigidly clamping the said pile element material on one side of the cutting means, holding the pile element material to be severed on the other side of the said cutting means between separators to prevent disturbance of the pile elements therebetween, cutting the pile element material between the clamping means and said separators, passing the severed pile element material between separators into a chamber to form alternating sections and separators therein, applying a vulcanizable cement material to the opposite exposed ends of the pile elements, applying a flexible backing material to each side of the pile element mass, vulcanizing the said cement material and cutting the resulting product in a plane between the flexible backing members to produce separate pile fabric products.

30. A method of manufacturing a cemented pile fabric material which comprises severing portions of fibre material to form sections of suitable height, passing the severed sections while under control to prevent disturbance of the fibres into a chamber to join a fibre mass of cut sections which is gradually fed into contact with a backing member, maintaining the fibre mass under a back pressure to provide the desired pile density in the mass, applying a vulcanizable cement material to a surface upon which a backing member is to be applied, passing a backing member into contact with the coated surface, vulcanizing the cement material to produce a permanent attachment of the fibres to the backing member, and thereafter cutting the pile elements in a plane at right angles to the fibres and substantially parallel to the flexible backing member.

31. In a method of making a cemented pile fabric the steps which comprise cutting a pile element material crosswise into sections, feeding the cut sections under pressure into a

- chamber to form a mass of upstanding sections with the cut ends exposed in parallel planes, replacing the feed pressure with independent holding means to maintain the pressure on the sections and to permit withdrawal of the said feeding means to feed additional sections into the said chamber, and withdrawing the said independent holding means during the feeding of the cut sections.
32. A method of making a cemented pile fabric which comprises cutting a batt crosswise into strips, feeding the cut strips under pressure into a chamber to form a mass of upstanding strips having the cut ends of the fibres exposed in substantially parallel planes, replacing the feed pressure means with independent holding means to permit withdrawing the feeding means, withdrawing the independent holding means when additional strips are fed into the chamber, feeding forward a strip of backing material into contact with the exposed ends of the fibres and cementing the fibres to the said backing material to form a continuous strip of pile fabric.
33. A method of making a cemented pile fabric which comprises cutting a pile element material crosswise into sections, feeding the cut sections under pressure into a chamber to form a mass of sections having the cut ends exposed in two substantially parallel planes, and cementing a flexible backing to the exposed ends of said sections in one of the planes within said chamber without releasing the pressure from the feed end of the said chamber, thus forming a product having a high pile density.
34. In a method of making a pile fabric product the steps which comprise severing sections of a pile element material while the sections to be severed are rigidly held in place, transferring the severed sections after each cutting operation to the main body of the severed pile element material by means of pressure applied laterally upon the severed sections, maintaining lateral pressure upon the main body of the fibres until a holding means is brought into operation against the said body, and thereafter releasing the pressure applying means and moving it away from the said holding means to leave a space for the insertion of another section of pile element material to be cut, moving another section of pile element material into the space between the said pressure applying means and said holding means, and repeating the cutting operation to provide additional cut sections.
35. An apparatus of the kind described which comprises an enclosed chamber, means for passing a mass of upstanding fibres into said enclosed chamber in contacting relation with opposite walls thereof, means for maintaining a lateral pressure on the fibre mass to crowd the fibres and to produce the

desired pile density, means for passing a flexible backing member into contact with one of the surfaces of said mass, and means for cementing the fibre ends to the said backing while the fibre mass is maintained under said pressure. 70

36. An apparatus for the making of a pile fabric which comprises a chamber, means for feeding under pressure a mass of substantially parallel upstanding fibres into the said chamber, the ends of the fibres being in contacting relation with opposite walls of the chamber, means for passing a flexible backing material into contact with the fibre ends at one face of the said mass, means for cementing the fibre ends to the said backing material and means for maintaining the mass under pressure during the cementing operation to obtain the desired pile density. 75

37. Apparatus for the making of a pile fabric which comprises a chamber, means for feeding under pressure a mass of fibres in substantially parallel relation into the said chamber, the fibres being in contacting relation with the opposite walls of the chamber to form continuous surfaces between which substantially parallel fibres run, means for passing a flexible backing material into contact with a continuous surface of the said mass, means for cementing the said backing material to a continuous surface formed by the fibres and means for maintaining the mass under pressure longitudinally of the mass during the cementing operation to obtain the desired pile density. 80

38. An apparatus for the making of a pile fabric which comprises a chamber, means for feeding a mass of substantially parallel upstanding fibres into the said chamber under continuously maintained pressure, the walls of the said chamber being so spaced apart that the ends of the fibres contact with the adjacent upper and lower walls thereof, means for applying back pressure to the fibre mass to compress the fibres to the desired density, and means for cementing the ends of the fibres on one side of the said mass to a backing material while the fibres are maintained under the said pressure to form a product of the desired density. 95

39. Apparatus for the making of a pile fabric which comprises a chamber, means for feeding under pressure a mass of fibres in substantially parallel relation into the chamber, the walls of said chamber being so spaced apart that the fibres in contact therewith form substantially continuous surfaces between which substantially parallel fibres run, means for applying back pressure to the fibre mass to compress the fibres to the desired density and means for cementing a backing material to a continuous surface formed by the fibres while the fibres are maintained under the said pressure. 100

40. An apparatus for the continuous pro- 105

- duction of pile fabric which comprises means for cutting fibre elements from a body of fibre material, means for clamping the fibre elements during the cutting operation to prevent displacement of the fibres in the said body of material, means for passing the cut elements into contact with a backing material, and means for cementing the cut elements to the backing material while the said elements are rigidly held in position. 5
- 10 41. An apparatus for the continuous production of a pile fabric product which comprises means for cutting fibre elements from a body of fibre material, means for clamping the fibre elements during the cutting operation to prevent displacement of the fibres in the said body of material, means for forming a mass of clamped fibre elements maintained under pressure, means for progressively moving the said mass into contact with a backing material, and means for cementing the cut elements to the backing material while the said elements are rigidly held in position. 15
- 20 42. An apparatus for the making of a pile fabric which comprises a chamber, separators for maintaining under pressure a mass of substantially parallel upstanding fibres, means for guiding the said separators and fibres into the said chamber, the opposite walls of which are movable to form contacting relation with the ends of the adjacent fibres, means for feeding the said separators and mass of fibres into the said chamber under pressure, means for coating one face of the said mass containing fibre ends with a vulcanizable cement material, means for passing a flexible backing material into contact with the said coated face of the fibres, means for exerting pressure on the backing material to bring it into pressure contact with the said coated face and means for vulcanizing the said cement material while the said backing material is held in pressure contact with the said coated face. 25
- 30 43. An apparatus of the kind described which comprises a chamber, means for passing a mass of fibres the ends of which are exposed in substantially two parallel planes into the said chamber in contacting relation with opposite walls thereof, means for applying lateral pressure to the fibre mass to move the mass forwardly in the said chamber and means for applying a back pressure to crowd the fibres together to produce the desired pile density and means for cementing a backing material to one of the exposed surfaces of the mass containing fibre ends to attach the said ends to the backing material while the said fibres are maintained under the 35 said lateral pressure. 40
44. An apparatus for the making of cemented pile fabric which comprises a chamber, means for passing a mass of fibres through the said chamber while the ends of the fibres are maintained in contacting rela- 45
- tion with the upper and lower walls of the said chamber, means for applying a feed pressure to the fibre mass, means for producing a back pressure in the chamber to crowd the fibres together to produce the desired pile density, and means for cementing a backing to one of the exposed surfaces of the fibre mass while the fibres are maintained under the said pressure. 50
- 70 45. An apparatus for the making of a cemented pile fabric which comprises means for cutting fibre elements from a body of fibre material, means for clamping the portion of the said fibre material to be severed to prevent displacement of the fibre elements therein during the cutting operation, means for progressively passing the severed portions into contact with a flexible backing material while maintaining the said portions in clamped relation, and means for securing the ends of the fibre elements to the said backing material while the said portions are held in clamped relation to said backing material. 75
- 80 46. An apparatus for the continuous production of a cemented pile fabric which comprises means for cutting fibre elements from a body of fibrous material, means for rigidly holding during the cutting operation the portion thereof to be severed, means for combining and feeding the severed elements in a mass into contact with a backing material, means for continuously feeding said backing material to which the severed fibre elements are to be attached, means for maintaining the severed portions in a fixed position relative to said backing material, and means for cementing the fibre elements to the said material while the said elements are still maintained in the said fixed relative position to form a continuous strip of pile fabric. 85
- 90 47. An apparatus for making a pile fabric which comprises a chamber, means for feeding under pressure a mass of upstanding fibres into the chamber, the fibres being of a length so as to contact with the opposite walls of the chamber to prevent bulging under the feed pressure and to maintain the fibres in fixed relation relative to each other with their ends exposed in two substantially parallel planes, means for feeding forward a strip of backing material over a support into contact with the exposed ends of the fibres on one side of the said mass, and means for securing the said fibres to the said strip to form a continuous strip of pile fabric. 95
- 100 48. An apparatus for the making of pile fabric which comprises means for clamping sections of fibres between separators, means for feeding the said sections maintained between the said separators into a chamber to form a mass of fibres rigidly held in position with the exposed ends thereof lying in two substantially parallel planes, means for feeding forward a strip of backing material 105
- 110
- 115
- 120
- 125
- 130

over a support, and means for cementing said fibres to the said strip to form a continuous strip of pile fabric.

49. Apparatus for making a pile fabric which comprises means for arranging fibres between a series of separators, means for passing said arranged fibres into a longitudinally extending chamber into substantially contacting relation with the opposite chamber walls, said fibres being arranged at substantially right angles to said walls, means for feeding forward a strip of backing material over a support, and means for cementing the said fibres to the said strip.

50. An apparatus for making a pile fabric which comprises means for clamping sections of fibres between separators, means for passing the said fibres into a chamber to form a mass of fibres having their ends exposed in two substantially parallel planes, means for feeding forward a strip of backing material over a support, means for cementing the said fibres to the said strip with a vulcanizable cement, and means for vulcanizing the said cement to permanently attach said fibres to said backing material.

51. An apparatus for making a pile fabric which comprises means for cutting sections from a pile element material, means for holding the portion of said pile element material to be severed during the cutting operation to prevent disturbance of the pile elements thereof, a chamber adapted to hold a series of cut sections of the said pile element material, means for passing controllably held cut sections into said chamber, means for feeding forward a strip of backing material into contact with ends of said pile element material, and means for cementing the said ends to said strip to form a continuous strip of pile fabric.

52. An apparatus for making a pile fabric which comprises means for cutting sections from a pile element material while the portions thereof to be severed are controllably held in position, a chamber, means for passing the severed sections side by side into said chamber to present the ends of the fibres thereof in two substantially parallel planes, means for feeding a strip of backing material into contact with the exposed ends of the fibres in one of said planes, and means for securing the backing material to the fibre ends to form a continuous strip of pile fabric.

53. An apparatus for making a pile fabric which comprises means for cutting sections crosswise from a pile element material, means for clamping the portions of the said pile element material to be severed so as to rigidly hold the fibres in fixed relation during cutting, means for feeding the severed portions forwardly while still clamped in position by said clamping means to form a packed mass of upstanding fibres, means for

feeding a strip of backing material into contact with the said fibres, and means for securing the ends of said fibres to the said strip to form a continuous strip of pile fabric.

54. An apparatus for the continuous manufacture of a cemented pile fabric which comprises means for cutting sections crosswise from a pile element material, means for holding the portions to be severed in place between separators during the cutting operation, means for continuously passing the severed sections while maintained in place between said separators into contact with a strip of backing material, means for continuously feeding the said strip, and means for securing the said sections to the backing material to form a strip of pile fabric.

55. An apparatus for making pile fabric which comprises means for cutting sections crosswise from a pile element material while the portions to be severed are held in place between separators of less width than the sections to be cut, an elongated chamber for receiving the cut sections, means for passing the severed sections while maintained in place between the separators into the said chamber in pressure contact with each other to form a mass of packed upstanding fibres having their ends in substantially parallel planes, means for passing the fibres into contact with a strip of backing material while the fibres are held in pressure contact with each other, and means for cementing the fibres to the said strip to form a pile fabric product.

56. An apparatus for making pile fabric which comprises means for continuously feeding a pile element material to be cut, means for holding the portion of the pile element material to be severed to rigidly clamp the fibres during the cutting operation, means for cutting the section to be severed beyond the portion engaged by said holding means, means for continuously feeding the severed sections in a mass into contact with a backing material, means for continuously feeding the backing material into contact with the ends of the pile elements of the severed sections, and means for permanently securing the ends of the said elements to the said strip to form a continuous strip of pile fabric.

57. An apparatus for making pile fabric which comprises means for feeding a pile element material to be cut into sections for forming the pile portion thereof, a series of separators, means for engaging under pressure contact each portion of the material to be severed with a separator, means for passing the severed portion into pressure contact with a mass of upstanding sections of pile element material previously severed, means for maintaining lateral pressure on the sections at right angles to the fibre lengths to attain the desired pile density of the mass,

means for passing the severed sections into pressure contact with a backing material and means for securing the ends of the elements of said sections to the backing material by means of a cement to form a strip of pile fabric.

58. An apparatus for making pile fabric which comprises means for feeding a pile element material to be cut, means for engaging the portion to be severed between separators having a less width than the sections to be severed, means for cutting the pile element material crosswise at a point beyond the said separators, means for passing the severed sections together with the separators into an enclosed space to form a mass of elements in which the ends thereof lie in substantially parallel planes, means for maintaining lateral pressure on the mass of cut sections to attain the desired density, means for combining the elements with strips of backing material on both sides of the mass by means of a cement material applied to the backing material and to the adjacent ends of the said elements, and means for slitting the attached elements in a plane between the backings to form two separate pile fabric products.

59. An apparatus for manufacturing cemented pile fabric which comprises means for cutting a pile element material, means for rigidly holding said material above and below the point of cutting in a manner to prevent substantial body displacement of the fibres of said material during the cutting operation, means for transferring the cut element material into contact with a backing member, and means for cementing the pile element material to the said backing member.

60. An apparatus for making cemented pile fabric which comprises means for rigidly holding a pile element material above and below the point of cutting to prevent the disturbance of the fibres in the sections to be cut, means for cutting the pile element material in a plane across the longitudinal dimension of the material, means for transferring the cut sections into contact with a backing member, and means for cementing the cut sections to the said backing member while the pile element material is still rigidly held to prevent displacement of the fibres until the fibres are permanently cemented to the said backing member.

61. An apparatus for making cemented pile fabric which comprises means for cutting a pile element material, means for rigidly holding the said material both above and below the point of cutting to prevent displacement of the fibres in the section to be severed, means for transferring the severed section into a chamber, means for applying lateral pressure to the severed sections in the said chamber to form a mass of fibres having a

high pile density, and means for cementing a backing material to the fibres while held under said pressure to form a pile fabric product having the desired density.

62. An apparatus for manufacturing a cemented pile fabric which comprises means for cutting a pile element material to provide unit pile elements, an elongated chamber, means uniting the cut elements into a mass in the said chamber so as to expose the ends thereof in substantially parallel plane surfaces, means for subjecting the mass of elements to lateral pressure to produce a high density and to endwise pressure to prevent bulging of the mass under said lateral pressure, and means for cementing the ends of said elements to a backing while the elements are maintained under said lateral and endwise pressure to form a product of the desired density.

63. An apparatus for manufacturing a cemented pile fabric which comprises means for cutting a batt into sections, a chamber, means for transferring the cut sections into the chamber so as to expose the fibre ends in two plane surfaces, means for maintaining the fibres substantially at right angles to the said surfaces, means for maintaining contact with said surfaces to prevent bulging of the fibre mass in the said chamber, means for passing the ends of said sections into contact with a flexible backing member, and means for cementing the backing member to one of said surfaces to provide a cemented pile fabric product.

64. An apparatus for manufacturing cemented pile fabric material which comprises means for feeding a batt in a longitudinal direction, means for cutting sections of the batt at right angles to the said longitudinal direction, means for rigidly holding the batt both above and below the point of cutting during the cutting operation, a chamber for holding the cut sections, means for transferring the cut sections to said chamber to form a fibre mass in which the pile elements are arranged at substantially right angles to the exposed surfaces of the mass, means for maintaining the fibre mass under lateral pressure to produce a high pile density in the mass, means for rigidly holding the cut section in the chamber to prevent disturbance of the fibre elements, and means for permanently cementing a flexible backing material to a surface of the mass containing fibre ends while the fibre elements are maintained under the said pressure to obtain a product having a high pile density.

65. An apparatus for manufacturing cemented pile fabric which comprises means for cutting a pile element material, means for intermittently feeding pile element material into a position to be cut by said cutting means, means for clamping the pile element material on each side of the said cutting means during the cutting operation, a cham-

- ber for receiving the cut sections, means for feeding the said material to the cutting means, means for rigidly holding the pile element material upon opposite sides of the cutting element during the cutting operation, a chamber adapted to hold the cut sections, 70 means for transferring the severed material into said chamber to join the mass of previously cut material therein, means for maintaining the fibres at substantially right angles to opposite exposed cut surfaces of the fibre mass, means for maintaining a back pressure on the mass of fibres while the material is being fed so as to provide the desired pile density in the mass, means for passing the cut fibres into a chamber in which a vulcanizable cement material is applied to the opposite exposed ends of the fibres, means for passing flexible backing material into contact with each of the exposed cut surfaces of the said mass, means for vulcanizing the said cement material while the fibre elements are maintained under the said pressure and means for cutting the fibre mass in a plane between the flexible backing members to provide separate pile fabric products. 90
66. An apparatus for manufacturing a cemented pile fabric which comprises means for intermittently feeding a mass of pile element material into a position to be cut by a cutting means, means for cutting said pile element material, means for clamping the pile element material on each side of the said cutting means during the cutting operation, means for controllably holding the fibres of the pile element material after being cut by 85 said cutting means, a chamber adapted to hold the cut sections, means for transferring the cut sections while maintained under control by said holding means into said chamber, means for maintaining the body of the fibre elements in said chamber at substantially right angles to the opposite exposed surfaces of the mass of fibres, means for applying a vulcanizable cement to the opposite exposed surfaces of the fibre mass, means for cementing a backing material to each side of the coated fibre elements, and means for cutting the fibre elements in a plane between the parallel backing members to provide two separate pile fabric products. 100
67. An apparatus for manufacturing a cemented pile fabric which comprises means for cutting pile element material from a mass of fibres, means for rigidly holding said material above and below the point of cutting, means for maintaining a pressure contact on the severed material, a chamber for holding the cut sections, means for passing the severed material into said chamber to unite with a mass of upstanding cut elements in 105 which the fibre ends are exposed at opposite surfaces of the fibre mass, whereby the fibre elements are arranged substantially at right angles to the exposed opposite surfaces of the mass, means for applying a cement material to each of the exposed surfaces of the mass while under said pressure, means for cementing a backing material to each of the exposed coated surfaces, and means for cutting the fibre mass in a plane between the backing members to provide two separate pile fabric products. 110
68. Apparatus for manufacturing a cemented pile fabric product which comprises means for cutting a pile element material intermittently, means for intermittently 115
69. An apparatus for the manufacture of cemented pile fabric material which comprises a cutting means, means for intermittently feeding a pile element material into cutting position with respect to said cutting means, means for rigidly holding the said pile element material on one side of the cutting means by a clamping means and on the other side of said cutting means between separators during the cutting operation, means for cutting the pile element material crosswise of the said material, a chamber, means for passing the severed sections maintained between separators into said chamber so as to form alternating sections and separators 120 therein, and means for permanently attaching a backing material to an exposed surface of the pile element material while the said pile element material is maintained under pressure. 125
70. Apparatus for manufacturing a pile fabric material which comprises means for severing portions from a fibre element material in sections of suitable height, means for passing the severed portions while under control to prevent disturbance of the fibres into a chamber of a slightly less height than the said sections to form a fibre mass, means for gradually feeding the said sections into contact with a backing member, means for maintaining the fibre mass under lateral pressure to provide the desired pile density in the mass, means for applying a vulcanizable cement material to the surfaces upon which flexible backing members are to be applied, means for passing flexible backing members into contact with the cement coated surfaces, means for applying pressure normally to the said backing members, means for vulcanizing the cement ma- 130

terial to produce a permanent attachment of the fibres to the backing members, and means for cutting the attached pile elements in a plane substantially parallel to the flexible 5 backing members.

71. An apparatus for making a cemented pile fabric which comprises means for cutting a pile element material crosswise into sections, means for feeding the cut sections 10 under pressure into a chamber to form a mass of upstanding sections with the cut ends exposed in parallel planes, means for replacing the feed pressure in the chamber with independent holding means to maintain the pressure 15 sure on the sections and to permit withdrawal of the said feeding means for the feeding of additional sections into the said chamber, and means for withdrawing the said independent holding means during the feeding 20 of the cut sections into said chamber.

72. An apparatus for making a pile fabric product which comprises means for severing sections of a pile element material while each section to be severed is rigidly held in place, 25 means for transferring the severed sections of the pile elements after each cutting operation to the main body of the severed pile element material by means of pressure applied laterally upon the severed sections, means for 30 maintaining lateral pressure upon the main body of the fibres until a holding means is brought into operation against the said body, and means for releasing the pressure applying means and moving it away to permit insertion of another section of cut pile elements 35 into said chamber without releasing lateral pressure upon the main body of the fibres.

73. In a machine of the kind described, a chamber, a plunger having recesses in the 40 face thereof adapted to feed material longitudinally into the said chamber under pressure, and a member adapted to cooperate with the recesses of said plunger to permit withdrawal of the plunger and to replace the pressure 45 sure of the said plunger against the said material.

74. In a machine of the kind described a chamber, a plunger having recesses in the 50 face thereof adapted to feed material longitudinally into the said chamber and to apply pressure to material therein, a holding means mounted at substantially the entrance to the said chamber so as to move at right angles to the movement of said plunger and adapted to 55 move into the said recesses in the forward position of the plunger to permit removal of the said plunger and replacing the longitudinal pressure thereof against the said material, and means for moving the said pressure 60 applying means into and out of the said recesses.

75. In a machine of the kind described, a cutting element comprising hardened steel rollers mounted in a frame, a knife edge 65 mounted in fixed position in the machine,

means for moving the said rollers across the knife edge, a pair of holding jaws mounted adjacent one side of the said frame for holding material to be cut, a chamber in which the cut material may be fed, a plunger for 70 feeding the cut material into the said chamber, and a holding means for preventing the cut material from moving out of the feed end of the chamber when the plunger is withdrawn. 75

76. In a machine of the kind described, a cutting element comprising hardened steel rollers mounted in removable housings on a knife bar, a knife edge mounted in fixed position in the machine, means for moving said 80 knife bar to cause movement of said rollers across the knife edge and to cut the fibre element material inserted between said rollers and said knife edge, means for feeding the fibre element material between said rollers 85 and said knife edge, a pair of holding jaws mounted on the feed side of said material for holding the material to be cut adjacent the chamber in which the cut material is to be fed, a plunger for forcing cut sections of 90 the material into the said chamber and a series of pins adapted to be moved into position in the feed end of the said chamber to hold the material in place at the feed end when said plunger is withdrawn. 95

77. In a machine of the character described, a cutting element comprising hardened steel rollers mounted on a knife bar, a knife edge mounted in fixed position in the machine, means for moving the said knife bar to bring the rollers across the said knife edge for cutting a section of pile element material inserted between said knife edge and rollers, a pair of holding jaws mounted on 100 the feed side of the said cutting element and adjacent thereto for holding the said pile element material during the cutting operation, means for passing a separator from a separator magazine into position in contact with the section of pile element material to be severed, a plunger for clamping the section to be severed between the said separator and a previously inserted separator, a chamber in 105 which the severed section and separators in contact therewith may be fed, and means for holding the severed sections and separators against movement outwardly through the feed end of the said chamber when the said plunger is withdrawn. 110

78. In a machine of the kind described, a chamber, a series of separators adapted to hold sections of pile element material between them, means for automatically passing a series of separators with sections of pile elements between them into the said chamber, a second chamber, means for continuously passing a flexible backing material into contact with one face of the pile element material, and means for continuously cementing 115 the pile element material to said backing 120

material as it is passed into contact therewith.

79. In a machine of the kind described, a chamber, a series of separators adapted to hold sections of pile element material, means in connection with said separators for automatically passing said sections of pile element material into the said chamber, means for continuously passing a flexible backing material into contact with one face of the pile element material and means for continuously cementing the pile element material to said backing material.

80. In a machine of the kind described, a chamber, a series of separators adapted to hold sections of pile element material between them, means for automatically passing a series of separators with sections of pile elements rigidly held in position between them into the said chamber, a second chamber, means for passing a flexible backing material through said second chamber into contact with one face of the said pile element material, means for cementing the backing to the pile element material, means for applying pressure normally to the backing material while the pile element material is being cemented to said backing, and means for applying pressure to feed the separators and pile element material through the said chambers and to obtain a predetermined pile density.

81. In a machine of the kind described, a chamber, a series of separators, means for automatically passing separators with upstanding sections of pile element material between adjacent separators into the said chamber, a second chamber, guide means for guiding the said separators into and through the said chambers, means for passing a flexible backing material through said second chamber into contact with the exposed ends of the pile element material at one surface thereof so that the pile element material will be at right angles to the plane of the said backing material, and means for cementing the pile element material to the said backing.

82. In a machine of the kind described, a chamber, a series of separators adapted to hold upstanding sections of pile element material between them, guide means for guiding the separators into the said chamber, means for automatically feeding said separators and pile element material into the said chamber, a second chamber having conveyor belts at each of the exposed faces of the pile element material adapted to be moved at the same rate as that of the material passing through the chamber, means for applying a vulcanizable rubber cement material to a surface of the fibre mass containing exposed ends of the fibres, and means for passing a flexible backing material into said second chamber into pressure contact with the coated ends of the fibres, and means for vulcanizing

said rubber cement to permanently attach the fibres to the said backing material.

83. In a machine of the kind described, a chamber, a series of separators adapted to hold upstanding sections of pile element material between them so that the ends of the fibres thereof project beyond the edges of the separators, guide means for guiding the separators into the said chamber, means for automatically feeding the said separators and sections into the said chamber, a second chamber having conveyor belts mounted so as to move in pressure contact with the said sections passing through the chamber, means for applying a vulcanizable rubber cement material to the ends of the fibres projecting on both sides of the said separators, means for passing two coated flexible backing members into contact with the fibre ends, one on each side of the body of fibres, means for vulcanizing the said cement material to permanently attach the said ends to the backing material, means for removing the said separators from between the fibres and backing members and means for slitting the said fibre elements in a plane between the backing members to obtain two pile fabric products.

84. In a machine of the kind described, a chamber, a series of separators adapted to hold cut sections of pile element material between them, means for automatically passing a series of separators with said cut sections of pile elements between them into the said chamber, a second chamber, means for continuously passing a flexible backing material through said second chamber into contact with the cut ends forming one face of the pile element material and means for continuously cementing the cut ends of the pile element material to said backing material.

85. Apparatus for the making of pile fabric comprising a chamber, a series of separators for holding cut sections of pile element material, means for automatically passing a series of said separators holding said cut sections into said chamber, means for continuously passing a flexible backing material into contact with one face of the said cut sections of pile element material and means for continuously cementing the said pile element material to said backing.

In testimony whereof, I affix my signature.
ERNEST H. WARD.

CERTIFICATE OF CORRECTION.

Patent No. 1,864,478.

June 21, 1932.

ERNEST H. WARD.

It is hereby certified that error appears in the printed specification of the above numbered patent requiring correction as follows: Page 6, line 29, for "verying" read varying, line 89, for "members" read member, and line 95, for "in" read is; page 7, line 43, strike out the comma after "batt"; page 9, line 38, after the word "set" insert a comma; page 10, line 2, for "movements" read movement; page 21, line 129, claim 15, strike out the comma after "continuously" and insert the same to follow the word "other" in same line; page 22, line 69, claim 19, after "pile" insert the word fabric; page 23, line 39, claim 26, after "fibres" insert a comma; and that the said Letters Patent should be read with these corrections therein that the same may conform to the record of the case in the Patent Office.

Signed and sealed this 1st day of November, A. D. 1932.

(Seal)

**M. J. Moore,
Acting Commissioner of Patents.**
